ABSTRACT

A display driver includes a plurality of source amplifiers configured to drive a plurality of source lines of a display panel, and an amplifier control system configured to control the source amplifiers. Each of the source amplifiers is configured to drive a source line with a drive voltage corresponding to a grayscale value specified by an image data associated with each of the source amplifiers. The amplifier control system is configured to control execution and stopping of an amplifying operation of each of the source amplifiers based on the image data associated with each of the source amplifiers. The grayscale value corresponding to black portions of the display panel.

SYSTEM AND METHOD FOR DISPLAY
POWER REDUCTION

CROSS REFERENCE

This application claims priority to Japanese Patent Application No. 2017-149235, filed on Aug. 1, 2017, the disclosure of which is incorporated herein by reference in its entirety.

TECHNICAL FIELD

The present disclosure relates to a display driver and a display device, more particularly to a technique for power consumption reduction of a display driver and/or a display device.

BACKGROUND

In a display device featuring always-on display (AOD) functionality, images are always displayed on a display panel when the AOD is executed. The images may contain information such as the current time or the date. In some instances, because only minimum information is displayed, a black display region often occupies an increased portion of the display panel. Thus, there is a need to reduce power consumption utilized to display the black display region to further reduce the power consumption of the display device or a display driver that drives the display panel of the display device.

SUMMARY

In one embodiment, a display driver includes a plurality of source amplifiers and an amplifier control system. Each of the source amplifiers is configured to drive a source line with a drive voltage corresponding to a grayscale value specified by image data associated with each of the source amplifiers. The amplifier control system is configured to control execution and stop of an amplifying operation of each of the source amplifiers, based on the image data associated with each of the source amplifiers.

In another embodiment, a display device includes: a display panel including a plurality of source lines; and a display driver. The display driver includes a plurality of source amplifiers and an amplifier control system. Each of the source amplifiers is configured to drive a source line with a drive voltage corresponding to a grayscale value specified by image data associated with each of the source amplifiers. The amplifier control system is configured to control execution and stop of an amplifying operation of each of the source amplifiers, based on the image data associated with each of the source amplifiers.

In still another embodiment, a method includes: driving a plurality of source lines of a display panel based on image data associated with source amplifiers; and controlling execution and stop of an amplifying operation of each of the source amplifiers, based on the image data associated with each of the source amplifiers.

BRIEF DESCRIPTION OF THE DRAWINGS

So that the manner in which the above recited features of the present disclosure can be understood in detail, a more particular description of the disclosure, briefly summarized above, may be had by reference to embodiments, some of which are illustrated in the appended drawings. It is to be

2

noted, however, that the appended drawings illustrate only some embodiments of this disclosure and are therefore not to be considered limiting of its scope, for the disclosure may admit to other equally effective embodiments.

FIG. 1 illustrates an example image according to one or more embodiments;

FIG. 2 is a block diagram schematically illustrating the configuration of a display device according to one or more embodiments;

FIG. 3 illustrates the configuration of pixels according to one or more embodiments;

FIG. 4 is a circuit diagram illustrating the configuration of pixel circuits according to one or more embodiments.

FIG. 5 is a block diagram illustrating the configuration of a display driver according to one or more embodiments;

FIG. 6A illustrates a table indicating the relationship between the grayscale values according to one or more embodiments;

FIG. 6B illustrates a table indicating the relationship between the grayscale values according to one or more embodiments;

FIG. 7A is a circuit diagram of a source amplifier according to one or more embodiments;

FIG. 7B is a circuit diagram of a source amplifier according to one or more embodiments;

FIG. 8 is a timing chart illustrating the operation of the display device according to one or more embodiments;

FIG. 9 illustrates amplifier turn-on signals according to one or more embodiments;

FIG. 10 is a block diagram illustrating a configuration of the display driver according to one or more embodiments;

FIG. 11 is a timing chart for a display driver according to one or more embodiments;

FIG. 12A is a block diagram illustrating a display device according to one or more embodiments;

FIG. 12B is a circuit diagram of a display panel according to one or more embodiments;

FIG. 13 is a block diagram of a display driver according to one or more embodiments;

FIG. 14 is a timing chart of a display device according to one or more embodiments;

FIG. 15 is a block diagram of a display driver according to one or more embodiments;

FIG. 16 is a block diagram illustrating the a display driver according to one or more embodiments;

FIG. 17 illustrates the waveform of an amplifier turn-on signal according to one or more embodiments;

FIG. 18 is a block diagram of a display driver according to one or more embodiments;

FIG. 19A is a circuit diagram of an NMOS pixel circuit according to one or more embodiments;

FIG. 19B is a circuit diagram of a PMOS pixel circuit according to one or more embodiments;

FIG. 20 is a block diagram illustrating a display driver according to one or more embodiments;

FIG. 21A illustrates a table indicating grayscale values according to one or more embodiments;

FIG. 21B illustrates a table indicating the correspondence relationship between the grayscale values according to one or more embodiments;

FIG. 22 is a block diagram illustrating a display driver according to one or more embodiments; and

FIG. 23 is a block diagram illustrating a display driver according to one or more embodiments.

DETAILED DESCRIPTION

In one or more embodiments, a source amplifier that supplies a drive voltage to a pixel circuit that performs black

display stops the amplifying operation thereof. Stopping the amplifying operation is achieved by stopping the operation of a current source included in the source amplifier. This operation effectively reduces the power consumption in performing black display.

It should be noted that "black" displayed when a source amplifier performing the amplifying operation may be different from "black" displayed when the source amplifier stops the amplifying operation, if the amplifying operation of the source amplifier is simply stopped.

FIG. 1 illustrates one example of an image in which this phenomenon occurs. Illustrated in FIG. 1 is one example of a display image in the case when source amplifiers stop the amplifying operations in supplying pixel circuits positioned in regions near the upper and lower ends of the display panel and the source amplifiers perform the amplifying operations in supplying pixel circuits positioned in the central region of the display panel.

In a normally black liquid crystal display panel, for example, black display may be achieved by driving pixel electrodes of pixel circuits to a voltage close to the common voltage level VCOM. The common voltage level VCOM is often different from the circuit ground level of the source amplifiers. A source amplifier may be configured to be able only to output a selected one of the power supply voltage, often referred to as power supply voltage VSP or VSN, and the circuit ground level GND when the amplifying operation thereof is stopped. In this case, the voltage level on the pixel electrode may be different between "black" for the case when the amplifying operation is performed in the source amplifier and "black" for the case when the amplifying operation is stopped, and this causes a difference in the brightness level.

In one or more embodiments, the drive voltage outputted to display "black" when the amplifying operation is provided by a source amplifier, that is, the drive voltage corresponding to black display is set to the power supply voltage or the circuit ground level. In one or more embodiments, the source amplifier is configured to stop the operation of a current source and output the drive voltage corresponding to black display, when the amplifying operation of the source amplifier is stopped. This effectively reduces the power consumption, while avoiding the problem of the difference in the brightness level of "black".

In the following, a description is given of various embodiments of the present disclosure with reference to the attached drawings. The same or corresponding components may be denoted by the same or corresponding reference numerals in the following description. It should be also noted that suffixes may be attached to reference numerals to distinguish the same components from each other.

FIG. 2 is a block diagram schematically illustrating the configuration of a display device 100 in one or more embodiments. The display device 100 includes a display panel 1 and a display driver 2. The display device 100 is configured to receive image data from an application processor 3, and display an image corresponding to the received image data on the display panel 1.

The display panel 1 includes a display region 4 and gate driver circuitry 5. Arranged in the display region 4 are a plurality of gate lines 6, a plurality of source lines 7 and a plurality of pixel circuits 8. The pixel circuits 8 are arrayed in rows and columns and each pixel circuit 8 is disposed at an intersection of the corresponding gate line 6 and source line 7. The gate driver circuitry 5 is configured to select a gate line 6 in response to gate control signals received from the display driver 2 and drive the selected gate line 6.

FIG. 3 illustrates the configuration of each pixel 10 of the display panel 1. Each pixel 10 includes three pixel circuits 8 that display red (R), green (G) and blue (B), respectively. A pixel circuit 8 displaying red is used as an R subpixel. Similarly, a pixel circuit 8 displaying green is used as a G subpixel, and a pixel circuit 8 displaying blue is used as a B subpixel. In this embodiment, each source line 7 is connected to pixel circuits 8 displaying the same color. In this embodiment, the number m of the source lines 7 is a multiple of six. For k being any natural number equal to or less than $m/3$, the $(3k-2)^{th}$ source line 7 is connected to pixel circuits 8 displaying red, the $(3k-1)^{th}$ source line 7 is connected to pixel circuits 8 displaying green, and the $(3k)^{th}$ source line 7 is connected to pixel circuits 8 displaying blue. In the following, a pixel circuit 8 displaying red may be referred to as R subpixel 8R. Similarly, pixel circuits 8 displaying green and blue may be referred to as G subpixel 8G and B subpixel 8B, respectively. The arrangement of the R subpixel 8R, the G subpixel 8G and the B subpixel 8B in a pixel 10 is not limited to that illustrated in FIG. 3. Some of the pixel circuits 8 or subpixels may be configured to display a color other than red, blue and green, such as white and yellow.

In this embodiment, a liquid crystal display panel is used as the display panel 1. FIG. 4 is a circuit diagram illustrating the configuration of each pixel circuit 8 in this embodiment. Each pixel circuit 8 includes a select transistor 8a and a pixel electrode 8b in this embodiment. The pixel electrode 8b is disposed opposed to a common electrode 8c and the space between the pixel electrode 8b and the common electrode 8c is filled with liquid crystal. The common electrode 8c is kept at the common voltage level VCOM. In general, one common electrode 8c is provided for multiple pixel circuits 8; in one embodiment, one common electrode 8c is provided for all the pixel circuits 8.

The display panel 1 operates in a normally black mode or normally white mode, depending on the characteristics of the liquid crystal filled between the pixel electrode 8b and the common electrode 8c. Normally black is a mode in which a pixel circuit 8 displays black, that is, the brightness level of the pixel circuit 8 is set to the allowed lowest brightness level, when the potential difference between the pixel electrode 8b and the common electrode 8c is zero in the pixel circuit 8. Normally white is a mode in which a pixel circuit 8 displays white, that is, the brightness level of the pixel circuit 8 is set to the allowed highest brightness level, when the potential difference between the pixel electrode 8b and the common electrode 8c is zero in the pixel circuit 8.

Referring back to FIG. 2, the source lines 7 of the display panel 1 are connected to the source outputs S_1 to S_m of the display driver 2, respectively. In this embodiment, in which the number m of the source lines 7 is a multiple of six, the number of the source outputs S_1 to S_m is also the multiple of six. In the following, the source line 7 connected to the source output S_i may be referred to as the source line 7_i, where "i" is a natural number equal to or less than m.

The display driver 2 drives the source lines 7₁ to 7_m connected to the source outputs S_1 to S_m in response to the image data received from the application processor 3. The display driver 2 also has the function of controlling the gate driver circuitry 5 of the display panel 1 by supplying the gate control signals to the gate driver circuitry 5.

It should be noted that, the display driver 2 may have the function of touch sensing to sense a contact of a conductive body, such as a human finger and a stylus, with the display panel 1 in addition to the functions of driving the display panel 1 and controlling the gate driver circuitry 5. In such an embodiment, a touch panel may be placed on the display

panel 1. Alternatively, sensing capacitors used for touch sensing may be incorporated in the display panel 1.

FIG. 5 is a block diagram illustrating the configuration of the display driver 2 according to one or more embodiments. Illustrated in FIG. 5 is the configuration of circuitry of the display driver 2 related to the driving of the source lines 7.

The display driver 2 includes an interface 11, a logic module 12, initial stage line latch circuitry 13, output stage line latch circuitry 14, DA converters (DACS) 15₁ to 15_m, source amplifiers 16₁ to 16_m, output switch circuitries 17₁ to 17_(m/2), data identification circuitries 18₁ to 18_m and amplifier control circuitries 19₁ to 19_m.

The interface 11 receives image data from the application processor 3 and forwards the received image data to the logic module 12. A display memory (not illustrated) may be disposed between the interface 11 and the logic module 12. In such an embodiment, the image data received by the interface 11 are temporarily stored in the display memory and the image data stored in the display memory are forwarded to the logic module 12.

The logic module 12 includes image data processing circuitry 12a and a display timing controller 12b. The image data processing circuitry 12a performs image data processing on the image data received from the interface 11, and sequentially forwards the image data obtained by the image data processing to the initial stage line latch circuitry 13 via a line latch bus 20. The display timing controller 12b controls the operation timing of the display driver 2.

The initial stage line latch circuitry 13 sequentially receives the image data from the image data processing circuitry 12a and forwards the received image data to the output stage line latch circuitry 14. The initial stage line latch circuitry 13 includes latches 13₁ to 13_m storing image data to be supplied to the DA converters 15₁ to 15_m, respectively. In this embodiment, the image data stored in the latches 13₁ to 13_m are 8-bit data.

The output stage line latch circuitry 14 receives the image data from the initial stage line latch circuitry 13 and forwards the received image data to the DA converters 15₁ to 15_m. The output stage line latch circuitry 14 includes latches 14₁ to 14_m, associated with the DA converters 15₁ to 15_m, respectively. The latches 14₁ to 14_m latches the image data from the latches 13₁ to 13_m of the initial stage line latch circuitry 13 at the beginning of each horizontal sync period, and forwards the latched image data to the DA converters 15₁ to 15_m, respectively. The output stage line latch circuitry 14 stores image data actually used to drive the source lines 7 in each horizontal sync period. In the following, the image data supplied from the latch 14_i to the DA converter 15_i is referred to as the image data D_i. In other words, the latches 14₁ to 14_m supplies the image data D₁ to D_m to the DA converters 15₁ to 15_m, respectively. In this embodiment, the image data D₁ to D_m are each 8-bit data.

The DA converters 15₁ to 15_m perform digital-analog conversion on the image data D₁ to D_m received from the latches 14₁ to 14_m, respectively, and output grayscale voltages corresponding to the grayscale values specified by the image data D₁ to D_m. In this embodiment, the odd-numbered DA converter 15_{2k-1} is configured to output a positive grayscale voltage for k being any natural number equal to or less than m/2, and the even-numbered DA converter 15_{2k} is configured to output a negative grayscale voltage. The terms "positive" and "negative" referred herein are defined with respect to the voltage level of the circuit ground of the display driver 2, that is, the circuit ground level GND.

The source amplifiers 16₁ to 16_m output drive voltages corresponding to the grayscale voltages received from the

DA converters 15₁ to 15_m, respectively. Operational amplifiers are used as the source amplifiers 16₁ to 16_m. In this embodiment, the odd-numbered source amplifier 16_{2k-1} is configured to receive a positive grayscale voltage from the DA converter 15_{2k-1} and output a positive drive voltage corresponding to the received grayscale voltage, for k being any natural number equal to or less than m/2. The even-numbered source amplifier 16_{2k} is configured to receive a negative grayscale voltage from the DA converter 15_{2k} and output a negative drive voltage corresponding to the received grayscale voltage. In this embodiment, the source amplifiers 16₁ to 16_m are configured as voltage followers, and output drive voltages having the same voltage levels as those of the grayscale voltages received from the DA converters 15₁ to 15_m.

FIGS. 6A and 6B illustrate tables indicating the correspondence relationship between the grayscale values specified by the image data and the grayscale voltages output from the DA converters 15. In one or more embodiments, a black display corresponds to a minimum brightness grayscale level. In the embodiments of FIGS. 6A and 6B, the grayscale value "00h" corresponds to black, that is, the lowest brightness level, and "FFh" corresponds to white, that is, the highest brightness level. FIG. 6A illustrates the correspondence relationship for the case when the display panel 1 operates in the normally black mode and FIG. 6B illustrates the correspondence relationship for the case when the display panel 1 operates in the normally white mode. In this embodiment, in which the source amplifiers 16₁ to 16_m are configured to output drive voltages having the same voltage levels as those of the grayscale voltages received from the DA converters 15₁ to 15_m, the correspondence relationship between the drive voltages and the grayscale values specified by the image data illustrated in FIGS. 6A and 6B can be considered as the same as that between the grayscale voltages and the grayscale values specified by the image data.

As illustrated in FIG. 6A, the grayscale voltage corresponding to the grayscale value "00h", which corresponds to black, is set to the circuit ground level GND, when the display panel 1 operates in the normally black mode. The voltage levels of the positive grayscale voltages are defined so that the voltage levels of the positive grayscale voltages are increased as the grayscale values specified by the image data are increased. In contrast, the voltage levels of the negative grayscale voltages are defined so that the voltage levels of the negative grayscale voltages are decreased as the grayscale values specified by the image data are increased.

When the display panel 1 operates in the normally white mode, on the other hand, the positive grayscale voltage corresponding to the grayscale value "00h", which corresponds to black, is set to the power supply voltage VSP, which is a positive power supply voltage supplied to the source amplifiers 16 configured to output positive drive voltages, that is, the odd-numbered source amplifiers 16. Additionally, the voltage levels of the positive grayscale voltages are defined so that the voltage levels of the positive grayscale voltages are decreased as the grayscale values specified by the image data are increased. This implies that the positive grayscale voltage is set to the highest voltage level when the image data specifies the grayscale value "00h", which corresponds to black.

On the other hand, the negative grayscale voltage corresponding to the grayscale value "00h", which corresponds to black, is set to the power supply voltage VSN, which is a negative power supply voltage supplied to the source amplifiers 16 configured to output negative drive voltages, that is,

the even-numbered source amplifiers **16**. Additionally, the voltage levels of the negative grayscale voltages are defined so that the voltage levels of the negative grayscale voltages are increased as the grayscale values specified by the image data are increased. This implies that the negative grayscale voltage is set to the lowest voltage level when the image data specifies the grayscale value “00h”, which corresponds to black.

Referring back to FIG. 5, the output switch circuitries **17**₁ to **17**_(m/2) are disposed to switch connections between the source amplifiers **16**₁ to **16**_m and the source outputs **S**₁ to **S**_m and to thereby achieve inversion drive, such as dot inversion drive and column inversion drive. Each output switch circuitry **17**_k includes straight switches **21**, **22** and cross switches **23** and **24**, and is configured to connect one of the outputs of the source amplifiers **16**_{2k-1} and **16**_{2k} to the source output **S**_(2k-1) and the other to the source output **S**_(2k).

The data identification circuitries **18**₁ to **18**_m and the amplifier control circuitries **19**₁ to **19**_m constitute an amplifier control system configured to control activation and deactivation of the source amplifiers **16**₁ to **16**_m, together with the display timing controller **12b** of the logic module **12**. In various embodiments, when an image data supplied to a DA converter **15** specifies the grayscale value “00h”, which corresponds to black, the amplifier control system stops the operation of the source amplifier **16** connected to the DA converter **15**, which drives the source line **7** associated with the image data. This operation effectively reduces the power consumption in displaying an image which includes an increased number of subpixels which display black.

In one embodiment, the data identification circuitries **18**₁ to **18**_m respectively identify whether the image data **D**₁ to **D**_m supplied to the DA converters **15**₁ to **15**_m specify the grayscale value “00h”, which corresponds to black, and output data identification signals **25**₁ to **25**_m indicative of the identification results. In one embodiment, the data identification signal **25**_i is set to “0” when the image data **D**_i supplied to the DA converter **15**_i specifies the grayscale value “00h”, and otherwise the data identification signal **25**_i is set to “1”.

The amplifier control circuitries **19**₁ to **19**_m generate individual amplifier control signals **27**₁ to **27**_m, respectively, in response to the data identification signals **25**₁ to **25**_m received from the data identification circuitries **18**₁ to **18**_m and the amplifier control signal **26** received from the display timing controller **12b**.

The amplifier control signal **26** supplied from the display timing controller **12b** is used to totally stop the amplifying operations of all of the source amplifiers **16**. When the amplifying operations of all of the source amplifiers **16** are configured to be totally stopped, the amplifier control signal **26** is deactivated. In such an embodiment, the amplifier control circuitries **19**₁ to **19**_m stop the amplifying operations of all of the source amplifiers **16**, independently of the data identification signals **25**₁ to **25**_m.

When the display panel **1** is driven to display an image, the amplifier control signal **26** is activated. In such an embodiment, the amplifier control circuitries **19**₁ to **19**_m generate the individual amplifier control signals **27**₁ to **27**_m in response to the data identification signals **25**₁ to **25**_m, respectively, to thereby control the execution and stop of the amplifying operations of the source amplifiers **16**₁ to **16**_m, respectively. In one embodiment, the amplifier control circuitry **19**_i generates the individual amplifier control signals **27**_i so that the source amplifier **16**_i performs the amplifying operation, when the data identification signal **25**_i is set to

“1”, that is, when the image data **D**_i supplied to the DA converter **15**_i does not specify the grayscale value “00h”. When the data identification signal **25**_i is set to “0”, that is, when the image data **D**_i supplied to the DA converter **15**_i specifies the grayscale value “00h”, on the other hand, the amplifier control circuitry **19**_i generates the individual amplifier control signals **27**_i so that the source amplifier **16**_i stops the amplifying operation. It should be noted that the execution and stop of the amplifying operations of the source amplifiers **16**₁ to **16**_m can be individually controlled.

FIG. 7A is a circuit diagram illustrating an example of the configuration of an odd-numbered source amplifier **16**_{2k-1}, which is configured to output a positive drive voltage, and FIG. 7B is a circuit diagram illustrating an example of the configuration of an even-numbered source amplifier **16**_{2k}, which is configured to output a negative drive voltage, where **k** is any natural number equal to or less than **m/2**. Each source amplifier **16** is configured to output from an output terminal **42** a drive voltage having the same voltage level as that of the grayscale voltage supplied from the corresponding DA converter **15** to an input terminal **41**. In FIGS. 7A and 7B, the grayscale voltage supplied to the relevant source amplifier **16** is denoted by the symbol “**VIN**” and the drive voltage supplied outputted from the relevant source amplifier **16** is denoted by the symbol “**VOUT**”.

The individual amplifier control signals **27** supplied to each source amplifier **16** include amplifier turn-on signals **AMPON_P** and **AMPON_N** and output control signals **AMPOUTH_N** and **AMPOUTL_P**.

The amplifier turn-on signals **AMPON_P** and **AMPON_N** are control signals to allow and stop the amplifying operation of the source amplifier **16**. The amplifier turn-on signals **AMPON_P** and **AMPON_N** are complementary each other and the source amplifier **16** performs the amplifying operation when the amplifier turn-on signals **AMPON_P** and **AMPON_N** are activated. In this embodiment, the amplifier turn-on signal **AMPON_P** is high active and the amplifier turn-on signal **AMPON_N** is low active. Accordingly, when the amplifier turn-on signals **AMPON_P** and **AMPON_N** are activated, the amplifier turn-on signal **AMPON_P** is set to the high level and the amplifier turn-on signal **AMPON_N** is set to the low level.

The output control signals **AMPOUTH_N** and **AMPOUTL_P** are a pair of control signals specifying the drive voltage to be outputted from the output terminal **42** when the amplifying operation is stopped. The output control signal **AMPOUTH_N** is a low-active signal and the output control signal **AMPOUTL_P** is a high-active signal. When the output control signals **AMPOUTH_N** and **AMPOUTL_P** are activated, the output control signal **AMPOUTH_N** is set to the low level and the output control signal **AMPOUTL_P** is set to the high level. Each source amplifier **16** operates in response to the amplifier turn-on signals **AMPON_P**, **AMPON_N** and the output control signals **AMPOUTH_N** and **AMPOUTL_P**.

Referring to FIG. 7A, the odd-numbered source amplifier **16**_{2k-1}, which is configured to output a positive drive voltage, includes a differential stage **31**, an output stage **32**, a VSP output switch **34**, a GND output switch **35**, a power line **36** supplied with the power supply voltage **VSP** and a ground line **37** supplied with the circuit ground level **GND**. The power supply voltage **VSP** is a positive power supply voltage, which is higher than the circuit ground level **GND**.

The differential stage **31** includes PMOS transistors **MP1**, **MP2**, NMOS transistors **MN1**, **MN2**, constant current sources **38**, **39**, active load circuitry **40**, an internal power line **43** and an internal ground line **44**.

The PMOS transistors MP1 and MP2 have sources commonly connected to a node N₁ to form a PMOS differential pair. The gate of the PMOS transistor MP1 is connected to the input terminal 41, and the gate of the PMOS transistor MP2 is connected to the output terminal 42. The drain of the PMOS transistor MP1 is connected to a node N5 in the active load circuitry 40, and the drain of the PMOS transistor MP2 is connected to a node N6 in the active load circuitry 40.

The NMOS transistors MN1 and MN2 have sources commonly connected to a node P₁ to form an NMOS differential pair. The gate of the NMOS transistor MN1 is connected to the input terminal 41, and the gate of the NMOS transistor MN2 is connected to the output terminal 42. The drain of the NMOS transistor MN1 is connected to a node N3 of the active load circuitry 40, and the drain of the NMOS transistor MN2 is connected to a node N4 of the active load circuitry 40.

The constant current source 38 is configured to supply a constant bias current to the node N1 and the constant current source 39 is configured to withdraw a constant bias current from the node N2. In this embodiment, the constant current source 38 includes a PMOS transistor MP3 having a source connected to the internal power line 43 and a drain connected to the node N1. A bias voltage VBIAS1_P is supplied to the gate of the PMOS transistor MP3. The constant current source 39 includes an NMOS transistor MN3 having a source connected to the internal ground line 44 and a drain connected to the node N2. A bias voltage VBIAS1_N is supplied to the gate of the NMOS transistor MN3.

The active load circuitry 40 includes PMOS transistors MP5, MP6, NMOS transistors MN5, MN6, and floating current sources 45 and 46.

The PMOS transistors MP5 and MP6 constitute a current mirror. The sources of the PMOS transistors MP5 and MP6 are commonly connected to the internal power line 43, and the drains of the PMOS transistors MP5 and MP6 are connected to the nodes N3 and N4, respectively. The gates of the PMOS transistors MP5 and MP6 are commonly connected to the drain of the PMOS transistor MP6, that is, the node N4.

NMOS transistors MN5 and MN6 constitute another current mirror. The sources of the NMOS transistors MN5 and MN6 are commonly connected to the internal ground line 44 and the drains of the NMOS transistors MN5 and MN6 are connected to the nodes N5 and N6, respectively. The gates of the NMOS transistors MN5 and MN6 are commonly connected to the drain of the NMOS transistor MP6, that is, the node N6.

The floating current source 45 is connected between the nodes N3 and N5 and configured to generate a constant bias current flowing from the node N3 to node N5. The floating current source 45 includes a PMOS transistor MP7 and an NMOS transistor MN7. The PMOS transistor MP7 has a source connected to the node N3, a drain connected to the node N5 and a gate supplied with a bias voltage VBIAS2_P. The NMOS transistor MN7 has a source connected to the node N5, a drain connected to the node N3 and a gate supplied with a bias voltage VBIAS2_N.

The floating current source 46 is connected between the node N4 and the node N6 and configured to generate a constant current flowing from the node N4 to the node N6. The floating current source 46 includes a PMOS transistor MP8 and an NMOS transistor MN8. The PMOS transistor MP8 has a source connected to the node N4, a drain connected to the node N6 and a gate supplied with the bias voltage VBIAS2_P. The NMOS transistor MN8 has a source

connected to the node N6, a drain connected to the node N4 and a gate supplied with the bias voltage VBIAS2_N.

A switch element, in this embodiment, a PMOS transistor MP4 is disposed between the power line 36 and the internal power line 43 of the differential stage 31, and another switch element, in this embodiment, an NMOS transistor MN4 is disposed between the ground line 37 and the internal ground line 44 of the differential stage 31. The PMOS transistors MP4 and the NMOS transistor MN4 are disposed to control the supply of the power supply voltage VSP and the circuit ground level GND to the differential stage 31.

The output stage 32 is configured to output a drive voltage VOUT in response to the potentials on the nodes N3 and N5 of the active load circuitry 40. The output stage 32 includes a PMOS transistor MP11, an NMOS transistor MN11 and capacitors C1 and C2. The PMOS transistor MP11 and the NMOS transistor MN11 both operate as an output transistor.

The PMOS transistor MP11 has a source connected to the power line 36 and a drain connected to the output terminal 42. The gate of the PMOS transistor MP11 is connected to the node N3 of the active load circuitry 40 of the differential stage 31 via a switch element, in this embodiment, a PMOS transistor MP9. The gate of the PMOS transistor MP11 is further connected to the power line 36 via the PMOS transistor MP10. The gate of the PMOS transistor MP9 is supplied with the amplifier turn-on signal AMPON_N, and the gate of the PMOS transistor MP10 is supplied with the amplifier turn-on signal AMPON_P.

The NMOS transistor MN11 has a source connected to the ground line 37 and a drain connected to the output terminal 42. The gate of the NMOS transistor MN11 is connected to the node N5 of the active load circuitry 40 of the differential stage 31 via a switch element, in this embodiment, an NMOS transistor MN9. The gate of the NMOS transistor MN11 is also connected to the ground line 37 via the NMOS transistor MN10. The gate of the NMOS transistor MN9 is supplied with the amplifier turn-on signal AMPON_P and the gate of the NMOS transistor MN10 is supplied with the amplifier turn-on signal AMPON_N.

The capacitors C1 and C2 provide phase compensation of the drive voltage outputted from the output terminal 42. The capacitor C1 is connected between the drain and gate of the PMOS transistor MP11, and the capacitor C2 is connected between the drain and gate of the NMOS transistor MN11.

The VSP output switch 34 is used to pull up the output terminal 42 to the power supply voltage VSP. In this embodiment, the VSP output switch 34 includes a PMOS transistor MP13. The PMOS transistor MP13 has a source connected to the power line 36 and a drain connected to the output terminal 42. The gate of the PMOS transistor MP13 is supplied with the output control signal AMPOUTH_N.

The GND output switch 35 is used to pull down the output terminal 42 to the circuit ground level GND. In this embodiment, the GND output switch 35 includes an NMOS transistor MN13. The NMOS transistor MN13 has a source connected to the ground line 37 and a drain connected to the output terminal 42. The gate of the NMOS transistor MN13 is supplied with the output control signal AMPOUTL_P.

When the source amplifier 16_{2k-1} illustrated in FIG. 7A performs the amplifying operation, the amplifier turn-on signals AMPON_N and AMPON_P are activated and the output control signals AMPOUTH_N and AMPOUTL_P are deactivated. When the amplifier turn-on signals AMPON_N and AMPON_P are activated, the PMOS transistor MP4 and the NMOS transistor MN4 are turned on to supply the power supply voltage VSP and the circuit ground level GND to the differential stage 31 from the power line 36 and the ground

line 37. This allows the constant current sources 38, 39 and the floating current sources 45 and 46 to generate the bias currents to operate the differential stage 31. Additionally, when the amplifier turn-on signals AMPON_N and AMPON_P are activated, the PMOS transistor MP9 and the NMOS transistor MN9 are turned on to connect the differential stage 31 to the output stage 32. This allows the source amplifier 16_{2k-1} to perform the amplifying operation. In this embodiment, the output terminal 42 is connected to the gate of the PMOS transistor MP2 of the PMOS differential pair of the differential stage 31 and the gate of the NMOS transistor MN2 of the NMOS differential pair, and accordingly the source amplifier 16_{2k-1} operates as a voltage follower.

When the amplifier turn-on signals AMPON_N and AMPON_P are deactivated, the source amplifier 16_{2k-1} stops the amplifying operation. In one embodiment, the PMOS transistor MP4 and the NMOS transistor MN4 are turned off in response to the deactivation of the amplifier turn-on signals AMPON_N and AMPON_P to stop supplying the power supply voltage VSP and the circuit ground level GND from the power line 36 and the ground line 37 to the differential stage 31. In this state, the constant current sources 38, 39 and the floating current sources 45 and 46 do not generate the bias currents, and therefore the differential stage 31 stops operating. Additionally, when the amplifier turn-on signals AMPON_N and AMPON_P are deactivated, the PMOS transistor MP9 and the NMOS transistor MN9 are turned off to disconnect the differential stage 31 from the output stage 32. In one or more embodiments, the PMOS transistor MP10 and the NMOS transistor MN10 are turned on to fix the gates of the PMOS transistor MP11 and the NMOS transistor MN11 to the power supply voltage VSP and the circuit ground level GND, respectively. This causes the source amplifier 16_{2k-1} to stop the amplifying operation.

The drive voltage outputted from the output terminal 42 is controllable on the output control signals AMPOUTH_N and AMPOUTL_P, when the source amplifier 16_{2k-1} does not perform the amplifying operation. When the output control signal AMPOUTH_N is activated and the output control signal AMPOUTL_P is deactivated, the PMOS transistor MP13 of the VSP output switch 34 is turned on to output the power supply voltage VSP from the output terminal 42. When the output control signal AMPOUTL_P is activated and the output control signal AMPOUTH_N is deactivated, the NMOS transistor MN13 of the GND output switch 35 is turned on to output the circuit ground level GND from the output terminal 42.

With reference to FIG. 7B, an even-numbered source amplifier 16_{2k}, which is configured to output a negative drive voltage, is configured similarly to the odd-numbered source amplifier 16_{2k-1}, except for that the power line 36 supplied with the power supply voltage VSP is replaced with a ground line 47 fixed to the circuit ground level GND and the ground line 37 fixed to the circuit ground level GND is replaced with a power line 48 supplied with a power supply voltage VSN, which is a negative power supply voltage.

In the even-numbered source amplifier 16_{2k}, which is configured to output a negative drive voltage, the PMOS transistor MP13 operates as a GND output switch 49 configured to output the circuit ground level GND to the output terminal 42 in response to the output control signal AMPOUTH_N. In one or more embodiments, the NMOS transistor MN13 operates as a VSN output switch 50 configured to output the power supply voltage VSN to the output terminal 42 in response to the output control signal AMPOUTL_P.

The configuration of the source amplifiers 16 may be variously modified. It should be noted however that commonly-used amplifiers include a current source generating a bias current and are configured to be able to stop the amplifying operation by stopping the operation of the current source. Also when differently-configured operational amplifiers are used as the source amplifiers 16, the source amplifiers 16 are configured to be able to stop the operation of a current source generating a bias current in response to the individual amplifier control signals 27 or the amplifier turn-on signals AMPON_N and AMPON_P.

In the following, the operation of the display device 100 according to one or more embodiments is described. First, a description is given of the case when the display panel 1 is operated in the normally black mode. In such an embodiment, the correspondence relationship between the grayscale values specified by the image data supplied to each DA converter 15 and the grayscale voltage outputted from the DA converter 15 is as illustrated in FIG. 6A. It should be noted that each DA converter 15 is configured to output the circuit ground level GND as the grayscale voltage, when an image data supplied thereto specifies the grayscale value “00h”, which corresponds to black. This means that a source amplifier 16 associated with an image data that specifies the grayscale value “00h” should output the circuit ground level GND.

In one or more embodiments, the straight switches 21 and 22 of the output switch circuitries 17₁ to 17_m are turned on and the outputs of the source amplifiers 16₁ to 16_m are connected to the source outputs S₁ to S_m, respectively. Although the output switch circuitries 17₁ to 17_m switch connections between the source amplifiers 16₁ to 16_m and the source outputs S₁ to S_m at a given cycle period when an inversion drive scheme is used, the execution of the inversion drive is of less importance in the technique disclosed in this specification.

Additionally, the amplifier control signal 26 is assumed to be activated by the display timing controller 12b. When an image is displayed on the display panel 1, the amplifier control signal 26 is activated to place the amplifier control circuitries 19₁ to 19_m into a state in which the amplifier control circuitries 19₁ to 19_m generate the individual amplifier control signals 27₁ to 27_m in response to the data identification signals 25₁ to 25_m received from the data identification circuitries 18₁ to 18_m.

Overall, the display device 100 of this embodiment operates as follows. In the display device 100 of this embodiment, the amplifying operation of a source amplifier 16 that supplies a drive voltage to a pixel circuit 8 which displays black is stopped, when the drive voltage is written into the pixel circuit 8. The stopping of the amplifying operation is achieved by stopping the operations of current sources included in the source amplifier 16, in this embodiment, the constant current sources 38, 39 and the floating current sources 45 and 46. This operation effectively reduces the power consumption when performing black display. Additionally, the source amplifier 16 is configured to output the drive voltage corresponding to black display, when the amplifying operation of the source amplifier 16 is stopped. A detailed description is given below of the operation of the display device 100 of this embodiment.

FIG. 8 is a timing chart illustrating an example of the operation of the display device 100 of this embodiment. Illustrated in FIG. 8 is the operation of the display device 100 of this embodiment in the Nth to (N+2)th horizontal sync period. In FIG. 8, the legend “HSYNC” represents a hori-

zontal sync signal, which is activated at the timing when each horizontal sync period begins.

In the N th horizontal sync period, image data are sequentially transferred from the image data processing circuitry 12a of the logic module 12 to the initial stage line latch circuitry 13 via the line latch bus 20. In FIG. 8, the image data sequentially transferred to the initial stage line latch circuitry 13 in the Nth horizontal sync period are denoted by the legends “A1” to “Am”. The image data A_1 to A_m are stored in the latches 13₁ to 13_m of the initial stage line latch circuitry 13.

In one or more embodiments, the image data A_2 and A_3 stored in the latches 13₂ and 13₃ of the initial stage line latch circuitry 13 specify the grayscale value “00h”, which corresponds to black, in the N th horizontal sync period. In various embodiments, the image data A_2 and A_3 specify the grayscale values with respect to the drive voltages outputted from the source outputs S_2 and S_3 .

In the $(N+1)^{\text{th}}$ horizontal sync period, the pixel circuits 8 are driven in response to the image data A_1 to A_m , which have been transferred to the initial stage line latch circuitry 13 in the N th horizontal sync period.

In one embodiment, when the $(N+1)^{\text{th}}$ horizontal sync period starts, the gate line 6 associated with the pixel circuits 8 to be driven in the $(N+1)$ horizontal sync period is activated and the image data A_1 to A_m are transferred from the initial stage line latch circuitry 13 to the output stage line latch circuitry 14. The image data A_1 to A_m are latched by the latches 14₁ to 14_m of the output stage line latch circuitry 14, and this allows supplying the image data A_1 to A_m to the DA converters 15₁ to 15_m. The DA converters 15₁ to 15_m generate the grayscale voltages corresponding to the grayscale values specified by the image data A_1 to A_m , and supply the grayscale voltages thus generated.

Since the image data A_2 and A_3 specify the grayscale value “00h”, which corresponds to black, the data identification signals 25₂ and 25₃ are set to “0” by the data identification circuitries 18₂ and 18₃ and the amplifier control circuitries 19₂ and 19₃ generate the individual amplifier control signals 27₂ and 27₃ so as to stop the amplifying operations of the source amplifiers 16₂ and 16₃ in response to the data identification signals 25₂ and 25₃. In other words, the amplifier turn-on signals AMPON_P and AMPON_N of the individual amplifier control signals 27₂ and 27₃, which are supplied to the source amplifiers 16₂ and 16₃, are deactivated. As described above, when the amplifier turn-on signals AMPON_P and AMPON_N are deactivated, the operations of the current sources of the source amplifiers 16₂ and 16₃, that is, the constant current sources 38, 39 and the floating current sources 45 and 46 in this embodiment, are stopped to stop the amplifying operations of the source amplifiers 16₂ and 16₃. In FIG. 8, the legend “AMPON_P (S2)” indicates the waveform of the amplifier turn-on signal AMPON_P supplied to the source amplifier 16₂ and the legend “AMPON_P(S3)” indicates the waveform of the amplifier turn-on signal AMPON_P supplied to the source amplifier 16₃.

In one or more embodiments, the amplifier control circuitry 19₂ activates the output control signal AMPOUTH_N of the individual amplifier control signals 27₂ and deactivates the output control signal AMPOUTL_P. In response to the activation of the output control signal AMPOUTH_N, the source amplifier 16₂, which is configured to output a negative drive voltage, sets the drive voltage outputted to the source output S2 to the circuit ground level GND. Similarly, the amplifier control circuitry 19₃ activates the output control signal AMPOUTL_P of the individual amplifier control

signals 27₃ and deactivates the output control signal AMPOUTH_N. In response to the activation of the output control signal AMPOUTL_P, the source amplifier 16₃, which is configured to output a positive drive voltage, sets the drive voltage outputted to the source output S3 to the circuit ground level GND. It should be noted that the grayscale voltage and the drive voltage corresponding to the grayscale value “00h”, which corresponds to black, are the circuit ground level GND, when the display panel 1 operates in the normally black mode. The source amplifiers 16₂ and 16₃ are controlled to stop the amplifying operations thereof, while outputting the drive voltages corresponding to the grayscale value “00h”.

The data identification signals 25 outputted from the data identification circuitries 18 other than the data identification circuitries 18₂ and 18₃ are set to “1”. Accordingly, the amplifier control circuitries 19 other than the amplifier control circuitries 19₂ and 19₃ generate the individual amplifier control signals 27 to allow the associated source amplifiers 16 to perform the amplifying operations. The source amplifiers 16 other than the source amplifiers 16₂ and 16₃ operate as voltage followers to output the drive voltages having the same voltage levels as those of the grayscale voltages received from the associated DA converters 15.

This operation effectively reduces the power consumption, since the source amplifiers 16₂ and 16₃ stop the amplifying operations, which are associated with the image data A_2 and A_3 specifying the grayscale value “00h”, which corresponds to black. In this operation, the source amplifiers 16₂ and 16₃ are placed into the state in which the source amplifiers 16₂ and 16₃ output the drive voltages corresponding to the grayscale value “00h”.

In parallel to the above-described operation in the $(N+1)$ horizontal sync period, image data are sequentially transferred to the initial stage line latch circuitry 13 from the image data processing circuitry 12a via the line latch bus 20. The image data sequentially transferred to the initial stage line latch circuitry 13 in the $(N+1)^{\text{th}}$ horizontal sync period are denoted by the legends “B1” to “Bm” in FIG. 8. The image data B_1 to B_m are stored in the latches 13₁ to 13_m of the initial stage line latch circuitry 13, respectively.

In one or more embodiments, the image data B_1 , B_3 and B_m transferred in the $(N+1)^{\text{th}}$ horizontal sync period to the latches 13₁, 13₃ and 13_m of the initial stage line latch circuitry 13 specify the grayscale value “00h”, which corresponds to black. The image data B_1 , B_3 and B_m specify the grayscale values with respect to the drive voltages outputted from the source outputs S_1 , S_3 and S_m , respectively.

In the $(N+2)^{\text{th}}$ horizontal sync period, the pixel circuits 8 are driven in response to the image data B_1 to B_m , which have been transferred to the initial stage line latch circuitry 13 in the $(N+1)^{\text{th}}$ horizontal sync period. The pixel circuits 8 are driven in the $(N+2)^{\text{th}}$ horizontal sync period similarly to the $(N+1)$ horizontal sync period, except for that the image data B_1 to B_m are used in place of the image data A_1 to A_m . Since the image data B_1 , B_3 and B_m specify the grayscale value “00h”, which corresponds to black, the amplifying operation of the source amplifiers 16₁, 16₃ and 16_m are stopped in the $(N+2)^{\text{th}}$ horizontal sync period.

In one embodiment, the data identification signals 25₁, 25₃ and 25_m are set to “0” by the data identification circuitries 18₁, 18₃ and 18_m and the amplifier control circuitries 19₁, 19₃ and 19_m generate the individual amplifier control signals 27₁, 27₃ and 27_m so as to stop the amplifying operations of the source amplifiers 16₁, 16₃ and 16_m in response to the data identification signals 25₁, 25₃ and 25_m. In other words, the amplifier turn-on signals AMPON_P and

AMPON_N of the individual amplifier control signals 27_1 , 27_3 and 27_m , which are supplied to the source amplifiers 16_1 , 16_3 and 16_m , are deactivated. As described above, when the amplifier turn-on signals AMPON_P and AMPON_N are deactivated, the operations of the current sources of the source amplifiers 16_1 , 16_3 and 16_m , that is, the constant current sources 38 , 39 and the floating current sources 45 and 46 in this embodiment, are stopped to stop the amplifying operation of the source amplifiers 16_1 , 16_3 and 16_m . In FIG. 8, the legend “AMPON_P(S1)”, “AMPON_P(S3)” and “AMPON_P(Sm)” indicate the waveforms of the amplifier turn-on signals AMPON_P supplied to the source amplifier 16_1 , 16_3 and 16_m , respectively.

In one or more embodiments, the amplifier control circuitry 19_1 , 19_3 and 19_m generate the individual amplifier control signals 27_1 , 27_3 and 27_m so that the drive voltages supplied from the source amplifiers 16_1 , 16_3 and 16_m to the source outputs S_1 , S_3 and S_m are set to the circuit ground level GND. In one embodiment, the amplifier control circuitries 19_1 and 19_3 activate the output control signals AMPOUTL_P of the individual amplifier control signals 27_1 and 27_3 and deactivate the output control signals AMPOUTH_N. The amplifier control circuitries 19_m , on the other hand, activates the output control signals AMPOUTH_N of the individual amplifier control signals 27_m and deactivates the output control signals AMPOUTL_P. This allows the source amplifiers 16_1 , 16_3 and 16_m to stop the amplifying operation while outputting the drive voltages corresponding to the grayscale value “00h”, which corresponds to black.

The data identification signals 25 outputted from the data identification circuitries 18 other than the data identification circuitries 18_1 , 18_3 and 18_m are set to “1”. Accordingly, the amplifier control circuitries 19 other than the amplifier control circuitries 19_1 , 19_3 and 19_m generate the individual amplifier control signals 27 to allow the associated source amplifiers 16 to perform the amplifying operations. The source amplifiers 16 other than the source amplifiers 16_1 , 16_3 and 16_m operate as voltage followers to output the drive voltages having the same voltage levels as those of the grayscale voltages received from the associated DA converters 15 .

A similar operation is performed when the display panel 1 operates in the normally white mode. In such an embodiment, the correspondence relationship between the grayscale value specified by the image data supplied to each DA converter 15 and the grayscale voltage outputted from the DA converter 15 is modified as illustrated in FIG. 6B and the drive voltage outputted from a source amplifier 16 when the source amplifier 16 stops the amplifying operation is accordingly modified.

In one embodiment, as illustrated in FIG. 6B, when an image data supplied to an odd-numbered DA converter 15_{2k-1} , which is configured to generate a positive grayscale voltage, specifies the grayscale value “00h”, which corresponds to black, the grayscale voltage outputted from the DA converter 15 is set to the power supply voltage VSP. When an image data supplied to an even-numbered DA converter 15_{2k} , which is configured to generate a negative grayscale voltage, specifies the grayscale value “00h”, the grayscale voltage outputted from the DA converter 15 is set to the power supply voltage VSN.

Additionally, the odd-numbered source amplifier 16_{2k-1} outputs the power supply voltage VSP when the amplifying operation of the source amplifier 16 is stopped, and the even-numbered source amplifier 16_{2k-1} outputs the power

supply voltage VSN when the amplifying operation of the source amplifier 16 is stopped.

In one embodiment, the data identification circuitry 18_{2k-1} associated with the odd-numbered source amplifier 16_{2k-1} sets the data identification signal 25_{2k-1} to “0”, when the image data D_{2k-1} supplied to the odd-numbered DA converter 15_{2k-1} specifies the grayscale value “00h”, which corresponds to black. The amplifier control circuitry 19_{2k-1} generates the individual amplifier control signals 27_{2k-1} so as to stop the amplifying operation of the source amplifier 16_{2k-1} in response to the data identification signal 25_{2k-1} being set to “0”. In other words, the amplifier turn-on signals AMPON_P and AMPON_N of the individual amplifier control signals 27_{2k-1} supplied to the source amplifier 16_{2k-1} are deactivated. As described above, when the amplifier turn-on signals AMPON_P and AMPON_N are deactivated, the operation of the current sources of the differential stage 31 , that is, the constant current sources 38 , 39 and the floating current sources 45 and 46 , of the source amplifier 16_{2k-1} is stopped to stop the amplifying operation of the source amplifier 16_{2k-1} .

In one or more embodiments, the amplifier control circuitry 19_{2k-1} activates the output control signal AMPOUTH_N and deactivates the output control signal AMPOUTL_P. The source amplifier 16_{2k-1} sets the drive voltage outputted therefrom to the power supply voltage VSP in response to the activation of the output control signal AMPOUTH_N; also see FIG. 7A. It should be noted that the positive grayscale voltage and the positive drive voltage that correspond to the grayscale value “00h”, which corresponds to black, are the power supply voltage VSP when the display panel 1 operates in the normally white mode. This implies that the source amplifier 16_{2k-1} is placed into the state in which the source amplifier 16_{2k-1} stops the amplifying operation and outputs the drive voltage corresponding to the grayscale value “00h”.

In one or more embodiments, the data identification circuitry 18_{2k} associated with the even-numbered source amplifier 16_{2k} sets the data identification signal 25_{2k} to “0”, when the image data D_{2k} supplied to the even-numbered DA converter 15_{2k} specifies the grayscale value “00h”, which corresponds to black. The amplifier control circuitry 19_{2k} generates the individual amplifier control signals 27_{2k} so as to stop the amplifying operation of the source amplifier 16_{2k} in response to the data identification signal 25_{2k} . In other words, the amplifier turn-on signals AMPON_P and AMPON_N of the individual amplifier control signals 27_{2k} supplied to the source amplifier 16_{2k} are deactivated. As described above, when the amplifier turn-on signals AMPON_P and AMPON_N are deactivated, the operation of the current sources of the differential stage 31 , that is, the constant current sources 38 , 39 and the floating current sources 45 and 46 in this embodiment, of the source amplifier 16_{2k} is stopped to stop the amplifying operation of the source amplifier 16_{2k} .

In one or more embodiments, the amplifier control circuitry 19_{2k} activates the output control signal AMPOUTL_P and deactivates the output control signal AMPOUTH_N. In response to the activation of the output control signal AMPOUTL_P, the source amplifier 16_{2k} sets the drive voltage outputted therefrom to the power supply voltage VSN; also see FIG. 7B. It should be noted that the negative grayscale voltage and the negative drive voltage that correspond to the grayscale value “00h”, which corresponds to black, are the power supply voltage VSN when the display panel 1 operates in the normally white mode. This implies that the source amplifier 16_{2k} is placed into the state in which

the source amplifier 16_{2k} stops the amplifying operation and outputs the drive voltage corresponding to the grayscale value “00h”.

FIG. 9 schematically illustrates the correspondence between an image displayed by the display device 100 of this embodiment and the waveforms of the amplifier turn-on signals AMPON_P supplied to the source amplifiers 16. For easiness of understanding, FIG. 9 illustrates the operation of the display device 100 under an assumption that the number m of the source outputs, that is, the number of the source amplifiers 16 is 20. In the example illustrated in FIG. 9, the image displayed on the display panel 1 includes characters “12:12”.

The upper part of FIG. 9 illustrates the association of the image and the source outputs S_1 to S_{20} , that is, the pixel circuits 8 of the display panel 1 and the source outputs S_1 to S_{20} . The lower part of FIG. 9 illustrates the states of the amplifier turn-on signals AMPON_P supplied to the respective source amplifiers 16 at the timing when the respective pixel circuits 8 of the display panel 1 are driven. In FIG. 9, the waveforms of the amplifier turn-on signals AMPON_P are illustrated under an assumption that the pixel circuits 8 are sequentially driven from left to right of the image. The legend “1H” in FIG. 9 represents one horizontal sync period.

In one or more embodiments, the source outputs S_1 to S_{13} , S_{19} and S_{20} are connected to pixel circuits 8 displayed as black during all the horizontal sync periods, and accordingly the source amplifiers 16 connected to the source outputs S_1 to S_{13} , S_{19} and S_{20} stop the amplifying operations during all of the horizontal sync periods. The amplifier turn-on signals AMPON_P supplied to the source amplifiers 16 connected to the source outputs S_1 to S_{13} , S_{19} and S_{20} are deactivated during all the horizontal sync periods.

The source amplifiers 16 connected to the source outputs S_{14} to S_{18} perform the amplifying operations only during horizontal sync periods during which the source amplifiers 16 are connected to pixel circuits 8 engaged to display the characters “12:12”. The amplifier turn-on signals AMPON_P supplied to the source amplifiers 16 connected to the source outputs S_{14} to S_{18} are activated during the horizontal sync periods during which the source amplifiers 16 are connected to pixel circuits 8 engaged to display the characters “12:12”, and deactivated during horizontal sync periods during which the source amplifiers 16 are connected to pixel circuits 8 which display black. The source amplifiers 16 connected to the source outputs S_{14} to S_{18} perform the amplifying operation only when the amplifier turn-on signals AMPON_P supplied thereto are activated. This operation effectively reduces the power consumption.

As described above, the display device 100 of this embodiment is configured so that the amplifying operations of source amplifiers 16 supplying drive voltages to pixel circuits 8 which display black are stopped, when the drive voltages are written into the pixel circuits 8. Additionally, in the display device 100 of this embodiment, the source amplifiers 16 are each configured to output the drive voltage corresponding to black when the amplifying operation thereof is stopped. This operation allows reducing the power consumption depending on the display image.

Although the data identification circuitries 18, which identify whether the image data supplied to the respective DA converters 15 specify the grayscale value corresponding to black, are provided for the respective source amplifiers 16 in the above-described embodiment, the logic module 12 may be configured to identify whether each image data specifies the grayscale value corresponding to black portions of the display panel in an alternative embodiment.

FIG. 10 is a block diagram illustrating the configuration of the display driver 2 in which the logic module 12 is configured to identify whether each image data specifies the grayscale value “00h”, which corresponds to black. In the configuration illustrated in FIG. 10, the data identification circuitries 18_1 to 18_m are removed and a data identification circuitry $12c$ is provided in the logic module 12. The initial stage line latch circuitry 13 includes latches 53_1 to 53_m in addition to the latches 13_1 to 13_m , which latches image data, and the output stage line latch circuitry 14 includes latches 54_1 to 54_m in addition to the latches 14_1 to 14_m , which latches image data. The data identification circuitry $12c$ is connected to the latches 53_1 to 53_m of the initial stage line latch circuitry 13 via an amplifier control bus 51 and the latches 53_1 to 53_m are connected to the latches 54_1 to 54_m of the output stage line latch circuitry 14, respectively. The outputs of the latches 54_1 to 54_m are connected to the amplifier control circuitries 19_1 to 19_m , respectively. The output signals supplied from the latches 54_1 to 54_m to the amplifier control circuitries 19_1 to 19_m are used as the data identification signals 25_1 to 25_m .

The display driver 2 illustrated in FIG. 10 schematically operates as follows. The data identification circuitry $12c$ identifies whether the image data specify the grayscale value “00h”, which corresponds to black, when the image data are sequentially transferred to the initial stage line latch circuitry 13 via the line latch bus 20 and outputs a data identification bit for each of the transferred image data. Each of the data identification bits is a one-bit data indicating whether the associated image data specifies the grayscale value “00h”. The data identification bits are transferred to the initial stage line latch circuitry 13 via the amplifier control bus 51 and stored in the latches 53_1 to 53_m . The data identification bits stored in the latches 53_1 to 53_m are latched by the latches 54_1 to 54_m of the output stage line latch circuitry 14. The latches 54_1 to 54_m supply data identification signals 25_1 to 25_m corresponding to the latched data identification bits to the amplifier control circuitries 19_1 to 19_m . The amplifier control circuitries 19_1 to 19_m operate as described above.

FIG. 11 is a timing chart illustrating an example of the operation of the display driver 2 illustrated in FIG. 10. Illustrated in FIG. 11 is the operation of the display device 100 of this embodiment during the N th to $(N+2)^{th}$ horizontal sync periods.

In the N th horizontal sync period, image data are sequentially transferred from the image data processing circuitry $12a$ of the logic module 12 to the initial stage line latch circuitry 13 via the line latch bus 20. In FIG. 11, the image data sequentially transferred to the initial stage line latch circuitry 13 in the N th horizontal sync period are denoted by the legends “A1” to “Am”. The image data A_1 to A_m are stored in the latches 13_1 to 13_m of the initial stage line latch circuitry 13.

In one or more embodiments, the data identification circuitry $12c$ identifies whether each of the image data A_1 to A_m , which are sequentially transferred to the initial stage line latch circuitry 13, specifies the grayscale value “00h”, which corresponds to black, to generate the data identification bits. The data identification circuitry $12c$ stores the data identification bits thus generated into the latches 53_1 to 53_m . For example, when the image data A_i transferred to the latch 13_i specifies the grayscale value “00h”, the data identification bit associated with the image data A_i is set to “0” and stored in the latch 53_i .

In one or more embodiments, the image data A_2 and A_3 stored in the latches 13_2 and 13_3 of the initial stage line latch circuitry 13 in the N th horizontal sync period specify the

grayscale value “00h”. In various embodiments, the image data A_2 and A_3 specify the grayscale values with respect to the drive voltages outputted from the source outputs S_2 and S_3 .

In such an embodiment, the data identification bits stored in the latches 53_2 and 53_3 of the initial stage line latch circuitry 13 are set to “0”. The data identification bits stored in the remaining latches 53 are set to “1”.

In the $(N+1)^{th}$ horizontal sync period, selected pixel circuits 8 are driven in response to the image data A_1 to A_m , which have been transferred to the initial stage line latch circuitry 13 in the N th horizontal sync period.

In one embodiment, the gate line 6 associated with the pixels 10 to be driven in the $(N+1)$ horizontal sync period is activated and the latches 14_1 to 14_m of the output stage line latch circuitry 14 latches the image data A_1 to A_m from the latches 13_1 to 13_m of the initial stage line latch circuitry 13 , respectively. The latches 14_1 to 14_m of the output stage line latch circuitry 14 supply the image data A_1 to A_m to the DA converters 15_1 to 15_m , respectively, and the DA converters 15_1 to 15_m generate grayscale voltages corresponding to the grayscale values specified in the image data A_1 to A_m , respectively. The grayscale voltages generated by the DA converters 15_1 to 15_m are supplied to the source amplifiers 16_1 to 16_m , respectively.

In one or more embodiments, the latches 54_1 to 54_m of the output stage line latch circuitry 14 latch the data identification bits from the latches 53_1 to 53_m of the initial stage line latch circuitry 13 . This results in that the data identification signals 25_2 and 25_3 are set to “0”, since the data identification bits associated with the image data A_2 and A_3 , which are latched by the latches 54_2 and 54_3 , are “0”. The amplifier control circuitries 19_2 and 19_3 generate the individual amplifier control signals 27_2 and 27_3 so as to stop the amplifying operations of the source amplifiers 16_2 and 16_3 , in response to the data identification signals 25_2 and 25_3 . In other words, the amplifier turn-on signals $AMPON\_P$ and $AMPON\_N$ of the individual amplifier control signals 27_2 and 27_3 , which are supplied to the source amplifiers 16_2 and 16_3 , are deactivated. As described above, when the amplifier turn-on signals $AMPON\_P$ and $AMPON\_N$ are deactivated, the operations of the current sources of the differential stage 31 of the source amplifiers 16_2 and 16_3 , that is, the constant current sources 38 , 39 and the floating current sources 45 and 46 , are stopped to stop the amplifying operations of the source amplifiers 16_2 and 16_3 . FIG. 11 illustrates the values of the data identification bits stored in the latches 54_2 and 54_3 together with the waveforms of the amplifier turn-on signals $AMPON\_P$ supplied to the source amplifier 16_2 and 16_3 .

Additionally, depending on whether the display panel 1 operates in the normally black mode or the normally white mode, the amplifier control circuitries 19_2 and 19_3 each activate one of the output control signals $AMPOUTH\_N$ and $AMPOUTL\_P$ for the respective individual amplifier control signals 27_2 and 27_3 , respectively, and deactivate the other.

When the display panel 1 operates in the normally black mode, the amplifier control circuitries 19_2 and 19_3 output the output control signals $AMPOUTH\_N$ and $AMPOUTL\_P$ so that the drive voltages supplied from the source amplifiers 16_2 and 16_3 to the source outputs S_2 and S_3 are set to the circuit ground level GND . It should be noted that the grayscale voltage and the drive voltage corresponding to the grayscale value “00h”, which corresponds to black, are the circuit ground level GND , when the display panel 1 operates in the normally black mode. This implies that the source amplifiers 16_2 and 16_3 are placed in the state in which the

source amplifiers 16_2 and 16_3 output the drive voltages corresponding to the grayscale value “00h”, while stopping the amplifying operation.

When the display panel 1 operates in the normally white mode, on the other hand, the amplifier control circuitry 19_2 outputs the output control signals $AMPOUTH\_N$ and $AMPOUTL\_P$ so that the drive voltage supplied from the source amplifiers 16_2 , which is configured to output a negative drive voltage, to the source output S_2 is set to the power supply voltage VSN , and the amplifier control circuitry 19_3 outputs the output control signals $AMPOUTH\_N$ and $AMPOUTL\_P$ so that the drive voltage supplied from the source amplifiers 16_3 , which is configured to output a positive drive voltage, to the source output S_3 is set to the power supply voltage VSP . It should be noted that, when the display panel 1 operates in the normally white mode, the positive grayscale voltage and the positive drive voltage corresponding to the grayscale value “00h”, which corresponds to black, are the power supply voltage VSP , and the negative grayscale voltage and the negative drive voltage corresponding to the grayscale value “00h” are the power supply voltage VSN . Also In such an embodiment, the source amplifiers 16_2 and 16_3 are placed in the state in which the source amplifiers 16_2 and 16_3 output the drive voltages corresponding to the grayscale value “00h”, while stopping the amplifying operations thereof.

The data identification signals 25 outputted from ones of the latches 54_1 to 54_m other than the latches 54_2 and 54_3 are set to “1”. Accordingly, the amplifier control circuitries 19 other than the amplifier control circuitries 19_2 and 19_3 generate the individual amplifier control signals 27 so that the associated source amplifiers 16 perform the amplifying operations. The source amplifiers 16 other than the source amplifiers 16_2 and 16_3 operate as voltage followers, and output the drive voltages having the same voltage levels as those of the grayscale voltages received from the associated DA converters 15 .

In parallel to the above-described operation in the $(N+1)$ horizontal sync period, image data are sequentially transferred to the initial stage line latch circuitry 13 from the image data processing circuitry $12a$ via the line latch bus 20 . The image data sequentially transferred to the initial stage line latch circuitry 13 in the $(N+1)^{th}$ horizontal sync period are denoted by the legends “ B_1 ” to “ B_m ” in FIG. 11. The image data B_1 to B_m are stored in the latches 13_1 to 13_m of the initial stage line latch circuitry 13 .

In one or more embodiments, the data identification circuitry $12c$ identifies whether each of the image data B_1 to B_m , which are sequentially transferred to the initial stage line latch circuitry 13 , specifies the grayscale value “00h”, which corresponds to black, to generate the data identification bits. The data identification circuitry $12c$ stores the data identification bits thus generated into the latches 53_1 to 53_m . For example, when the image data B_i transferred to the latch $13i$ specifies the grayscale value “00h”, the data identification bit associated with the image data B_i is set to “0” and stored in the latch $53i$.

In one or more embodiments, the image data B_1 , B_3 and B_m stored in the latches 131 , 133 and $13m$ of the initial stage line latch circuitry 13 in the $(N+1)^{th}$ horizontal sync period specify the grayscale value “00h”. The image data B_1 , B_3 and B_m specify the grayscale values with respect to the drive voltages outputted from the source outputs S_1 , S_3 and S_m . In such an embodiment, the data identification bits stored in the latches 531 , 533 and $53m$ of the initial stage line latch circuitry 13 are set to “0”. The data identification bits stored in the remaining latches 53 are set to “1”.

In the $(N+2)^{th}$ horizontal sync period, selected pixel circuits **8** are driven in response to the image data B_1 to B_m , which have been transferred to the initial stage line latch circuitry **13** in the $(N+1)^{th}$ horizontal sync period. The pixel circuits **8** are driven in the $(N+2)^{th}$ horizontal sync period similarly to the $(N+1)^{th}$ horizontal sync period, except for that the image data B_1 to B_m are used in place of the image data A_1 to A_m . Since the image data B_1 , B_3 and B_m specify the grayscale value “00h”, which corresponds to black, the amplifying operations of the source amplifiers **16₁**, **16₃** and **16_m** are stopped in the $(N+2)^{th}$ horizontal sync period.

In one embodiment, since the data identification bits associated with the image data B_1 , B_3 and B_m , that is, the data identification bits latched by the latches **54₁**, **54₃** and **54_m**, are “0”, the data identification signals **25₁**, **25₃** and **25_m** are set to “0”. The amplifier control circuitries **19₁**, **19₃** and **19_m** generate the individual amplifier control signals **27₁**, **27₃** and **27_m**, so as to stop the amplifying operations of the source amplifiers **16₁**, **16₃** and **16_m** in response to the data identification signals **25₁**, **25₃** and **25_m**. In other words, the amplifier turn-on signals **AMPON_P** and **AMPON_N** of the individual amplifier control signals **27₁**, **27₃** and **27_m**, which are supplied to the source amplifiers **16₁**, **16₃** and **16_m**, are deactivated. As described above, when the amplifier turn-on signals **AMPON_P** and **AMPON_N** are deactivated, the operations of the current sources of the differential stage **31** of the source amplifiers **16₁**, **16₃** and **16_m**, that is, the constant current sources **38**, **39** and the floating current sources **45** and **46**, are stopped to stop the amplifying operations of the source amplifiers **16₁**, **16₃** and **16_m**.

In one or more embodiments, depending on whether the display panel **1** operates in the normally black mode or the normally white mode, the amplifier control circuitries **19₁**, **19₃** and **19_m** each activate one of the output control signals **AMPOUTH_N** and **AMPOUTL_P** for the respective individual amplifier control signals **27₁**, **27₃** and **27_m**, respectively, and deactivate the other of the output control signals **AMPOUTH_N** and **AMPOUTL_P**.

When the display panel **1** operates in the normally black mode, the amplifier control circuitries **19₁**, **19₃** and **19_m** output the output control signals **AMPOUTH_N** and **AMPOUTL_P** so that the drive voltages supplied from the source amplifiers **16₁**, **16₃** and **16_m** to the source outputs **S₁**, **S₃** and **S_m** are set to the circuit ground level GND. It should be noted that the grayscale voltage and the drive voltage corresponding to the grayscale value “00h”, which corresponds to black, are the circuit ground level GND, when the display panel **1** operates in the normally black mode.

When the display panel **1** operates in the normally white mode, on the other hand, the amplifier control circuitry **19₁** and **19₃** output the output control signals **AMPOUTH_N** and **AMPOUTL_P** so that the drive voltages supplied from the source amplifiers **16₁** and **16₃** to the source outputs **S₁** and **S₃** are set to the power supply voltage **VSP**, and the amplifier control circuitry **19_m** outputs the output control signals **AMPOUTH_N** and **AMPOUTL_P** so that the drive voltage supplied from the source amplifiers **16_m** to the source output **S_m** is set to the power supply voltage **VSN**. It should be noted that, when the display panel **1** operates in the normally white mode, the positive grayscale voltage and the positive drive voltage corresponding to the grayscale value “00h”, which corresponds to black, are the power supply voltage **VSP**, and the negative grayscale voltage and the negative drive voltage corresponding to the grayscale value “00h” are the power supply voltage **VSN**.

The data identification signals **25** outputted from ones of the latches **54₁** to **54_m** other than the latches **54₁**, **54₃** and **54_m**

are set to “1”. Accordingly, the amplifier control circuitries **19** other than the amplifier control circuitries **19₁**, **19₃** and **19_m** generate the individual amplifier control signals **27** so that the associated source amplifiers **16** perform the amplifying operations. The source amplifiers **16** other than the source amplifiers **16₁**, **16₃** and **16_m** operate as voltage followers, and output the drive voltages having the same voltage levels as those of the grayscale voltages received from the associated DA converters **15**.

Also in the configuration and operation illustrated in FIGS. 10 and 11, the amplifying operation of a source amplifier **16** which supplies a drive voltage to a pixel circuit **8** that displays black is stopped when the drive voltage is written into the pixel circuit **8**. Additionally, the source amplifier **16** is configured to output the drive voltage corresponding to black portions of the display panel when the amplifying operation thereof is stopped. This operation effectively reduces the power consumption, depending on the display image.

FIG. 12A is a block diagram illustrating the configuration of a display device **100A** in accordance to one or more embodiments. Also in one or more embodiments, the amplifying operation of a source amplifier **16** which supplies a drive voltage to a pixel circuit **8** that displays black is stopped when the drive voltage is written into the pixel circuit **8**, and the source amplifier **16** is configured to output the drive voltage corresponding to black when the amplifying operation thereof is stopped. The display device **100A** is further configured to be adapted to the so-called time-divisional drive scheme.

In one embodiment, the display driver **2A** includes $m/3$ source outputs **S₁** to **S_(m/3)** and the display panel **1A** includes $m/3$ panel input terminals **9₁** to **9_(m/3)** and $m/3$ switch circuitries **60₁** to **60_(m/3)**, where m is the number of source lines **7** of the display panel **1A**; in embodiment, m is a multiple of six. In this embodiment, the source outputs **S₁** to **S_(m/3)** of the display driver **2A** are respectively connected to the panel input terminals **9₁** to **9_(m/3)**, which are connected to the switch circuitries **60₁** to **60_(m/3)**, respectively.

As illustrated in FIG. 12B, each switch circuitry **60_k** is connected to three source lines **7_{3k-2}**, **7_{3k-1}** and **7_{3k}** and configured to connect a selected one of the source lines **7_{3k-2}**, **7_{3k-1}** and **7_{3k}** to the panel input terminal **9_k**, that is, the corresponding source output **S_k**, in response to control signals **SW₁** to **SW₃**. In this embodiment, each switch circuitry **60_k** includes a switch **61** connected between the panel input terminal **9_k** and the source line **7_{3k-2}**, a switch **62** connected between the panel input terminal **9_k** and the source line **7_{3k-1}**, and a switch **63** connected between the panel input terminal **9_k** and the source line **7_{3k}**. The switch **61** is turned on to connect the source line **7_{3k-2}** to the panel input terminal **9_k** when the control signal **SW₁** is activated. Similarly, the switch **62** is turned on to connect the source line **7_{3k-1}** to the panel input terminal **9_k** when the control signal **SW₂** is activated, and the switch **63** is turned on to connect the source line **7_{3k}** to the panel input terminal **9_k** when the control signal **SW₃** is activated.

In this embodiment, the $(3k-2)^{th}$ source line **7_{3k-2}** is connected to pixel circuits **8** displaying red, that is, R subpixels **8R**, the $(3k-1)^{th}$ source line **7_{3k-1}** is connected to pixel circuits **8** displaying green, that is, G subpixels **8G**, and the $(3k)^{th}$ source line **7_{3k}** is connected to pixel circuits **8** displaying blue, that is, B subpixels **8B**, where k is any natural number equal to or less than $m/3$. Accordingly, the source output **S_k** of the display driver **2A** is connected to R subpixels **8R** when the control signal **SW₁** is activated. Similarly, the source output **S_k** is connected to G subpixels

8G when the control signal SW2 is activated, and the source output Sk is connected to B subpixels 8B when the control signal SW3 is activated. As described later, in this embodiment, the control signals SW1, SW2 and SW3 are sequentially activated in each horizontal sync period to achieve time-divisional driving of the R subpixels 8R, G subpixels 8G and B subpixels 8B in each horizontal sync period.

FIG. 13 is a block diagram illustrating the configuration of the display driver 2A according to one or more embodiments. Illustrated in FIG. 13 is the configuration of circuitry related to the operation of outputting drive voltages from two source outputs S1 and S2 in the display driver 2A.

In the display driver 2A, in which the number of the source outputs is $m/3$, the numbers of the DA converters 15, the source amplifiers 16, the data identification circuitries 18 and the amplifier control circuitries 19 are each $m/3$ and the number of the output switch circuitries 17 is $m/6$.

In one or more embodiments, the initial stage line latch circuitry 13 includes R latches 13R₁ to 13R_{m/3}, G latches 13G₁ to 13G_{m/3} and B latches 13B₁ to 13B_{m/3}. Similarly, the output stage line latch circuitry 14 includes R latches 14R₁ to 14R_{m/3}, G latches 14G₁ to 14G_{m/3} and B latches 14B₁ to 14B_{m/3}. Illustrated in FIG. 13 are two of the R latches 13R₁ to 13R_{m/3}, two of the G latches 13G₁ to 13G_{m/3}, two of the B latches 13B₁ to 13B_{m/3}, two of the R latches 14R₁ to 14R_{m/3}, two of the G latches 14G₁ to 14G_{m/3} and two of the B latches 14B₁ to 14B_{m/3}. The R latches 13R₁ to 13R_{m/3} and 14R₁ to 14R_{m/3} are used to store image data specifying the grayscale values of the R subpixels 8R. Similarly, the G latches 13G₁ to 13G_{m/3} and 14G₁ to 14G_{m/3} are used to store image data specifying the grayscale values of the G subpixels 8G, and the B latches 13B₁ to 13B_{m/3} and 14B₁ to 14B_{m/3} are used to store image data specifying the grayscale values of the B subpixels 8B. The R latches 14R₁ to 14R_{m/3}, the G latches 14G₁ to 14G_{m/3} and the B latches 14B₁ to 14B_{m/3} of the output stage line latch circuitry 14 are connected to the R latches 13R₁ to 13R_{m/3}, the G latches 13G₁ to 13G_{m/3} and the B latches 13B₁ to 13B_{m/3} of the initial stage line latch circuitry 13.

Additionally, the display driver 2A includes RGB selectors 64₁ to 64_{m/3}. Each RGB selector 64_k connects a selected one of the R latch 14R_k, G latch 14G_k and B latch 14B_k of the output stage line latch circuitry 14 to the DA converter 15_k in response to a RGB select signal 65 received from the display timing controller 12_b. The image data stored in the latch selected by the RGB selector 64_k is supplied to the DA converter 15_k. In one or more embodiments, the data identification circuitry 18_k identifies whether the image data supplied to the DA converter 15_k specifies the grayscale value “00h”, which corresponds to black, and generates the data identification signal 25_k. The amplifier control circuitry 19_k generates the individual amplifier control signals 27_k in response to the data identification signal 25_k.

A description is then given of the operation of the display device 100A according to one or more embodiments. In one or more embodiments, the straight switches 21 and 22 of the output switch circuitries 17₁ to 17_{m/6} are turned on, and the outputs of the source amplifiers 16₁ to 16_{m/3} are connected to the source outputs S₁ to S_(m,3), respectively. Although the output switch circuitries 17₁ to 17_{m/6} switch connections between the source amplifiers 16₁ to 16_{m/3} and the source outputs S₁ to S_(m,3) at a given cycle period when an inversion drive scheme is used, the execution of the inversion drive is of less importance in the technique disclosed in this specification.

FIG. 14 is a timing chart illustrating an example of the operation of the display device 100A in according to one or

more embodiments. Illustrated in FIG. 14 is the operation of circuitry associated with the source outputs S1 and S2 of the display driver 2A. At the timing immediately before the Nth horizontal sync period is started, image data specifying the grayscale value “00h”, which corresponds to black, are stored in the G latch 13G₁ and B latch 13B₂ of the initial stage line latch circuitry 13 and image data specifying grayscale values different from the grayscale value “00h” are stored in the R latch 13R₁, B latch 13B₁, R latch 13R₂ and the G latch 13G₂ of the initial stage line latch circuitry 13. Additionally, the amplifier control signal 26 is activated by the display timing controller 12_b.

When the Nth horizontal sync period is started, the output stage line latch circuitry 14 latches image data from the initial stage line latch circuitry 13. It should be noted that the image data specifying the grayscale value “00h”, which corresponds to black, are latched by the G latch 14G₁ and the B latch 14B₂ of the output stage line latch circuitry 14.

Additionally, the gate line 6 associated with the pixels 10 to be driven in the Nth horizontal sync period is selected.

This is followed by driving the R subpixels 8R connected to the selected gate line 6. In one embodiment, the control signal SW1 is activated to connect the source lines 7 connected to the R subpixels 8R are connected to the source outputs S₁ to S_(m,3). Furthermore, the RGB selectors 64 select the R latches 14R₁ to 14R_{m/3} of the output stage line latch circuitry 14 in response to the RGB select signal 65 and connect the R latches 14R₁ to 14R_{m/3} to the DA converters 15₁ to 15_{m/3}, respectively. The DA converters 15₁ to 15_{m/3} generate grayscale voltages corresponding to the grayscale values specified by the image data received from the R latches 14R₁ to 14R_{m/3}, and supply the generated grayscale voltages to the source amplifiers 16₁ to 16_{m/3}.

In the operation illustrated in FIG. 14, none of the image data supplied from the R latches 14R₁ to 14R_{m/3} to the DA converters 15₁ to 15_{m/3} specifies the grayscale value “00h”, which corresponds to black. Accordingly, the data identification circuitries 18₁ to 18_{m/3} set the data identification signals 25₁ to 25_{m/3} to “1”. The amplifier control circuitries 19₁ to 19_{m/3} generate the individual amplifier control signals 27₁ to 27_{m/3} to allow the source amplifiers 16₁ to 16_{m/3} to perform the amplifying operations. The source amplifiers 16₁ to 16_{m/3} operate as voltage followers and output drive voltages having the same voltage levels as those of the grayscale voltages received from the associated DA converters 15₁ to 15_{m/3}.

This is followed by driving the G subpixels 8G connected to the selected gate line 6. In one embodiment, the control signal SW2 is activated to connect the source lines 7 connected to the G subpixels 8G are connected to the source outputs S₁ to S_(m,3). Furthermore, the RGB selectors 64 select the G latches 14G₁ to 14G_{m/3} of the output stage line latch circuitry 14 in response to the RGB select signal 65 and connect the G latches 14G₁ to 14G_{m/3} to the DA converters 15₁ to 15_{m/3}, respectively. The DA converters 15₁ to 15_{m/3} generate grayscale voltages corresponding to the grayscale values specified by the image data received from the G latches 14G₁ to 14G_{m/3}, and supply the generated grayscale voltages to the source amplifiers 16₁ to 16_{m/3}.

In the embodiment illustrated in FIG. 14, the image data supplied from the G latches 14G₁ to the DA converters 15₁ specifies the grayscale value “00h”, which corresponds to black, and accordingly the data identification circuitry 18₁ sets the data identification signal 25₁ to “0”. The amplifier control circuitry 19₁ generates the individual amplifier control signals 27₁ so as to stop the amplifying operation of the source amplifiers 16₁. In other words, the amplifier turn-on

signals AMPON_P and AMPON_N of the individual amplifier control signals 271, which are supplied to the source amplifier 161, are deactivated. In FIG. 14, the waveform of the amplifier turn-on signal AMPON_P of the individual amplifier control signals 271 is indicated by the legend “AMPON_P(S1)”. 5

Additionally, depending on whether the display panel 1 operates in the normally black mode or the normally white mode, the amplifier control circuitries 191 activates one of the output control signals AMPOUTH_N and AMPOUTL_P of the individual amplifier control signals 271, and deactivates the other. When the display panel 1 operates in the normally black mode, the amplifier control circuitry 191 activates the output control signal AMPOUTL_P and deactivates the output control signal AMPOUTH_N. In response to the activation of the output control signal AMPOUTL_P, the source amplifier 161 sets the drive voltage to be supplied to S₁ to the circuit ground level GND. When the display panel 1 operates in the normally white mode, the amplifier control circuitry 191 activates the output control signal AMPOUTH_N and deactivates the output control signal AMPOUTL_P. In response to the activation of the output control signal AMPOUTH_N, the source amplifier 161, which is configured to output a positive drive voltage, sets the drive voltage to be supplied to the source output S₁ to the power supply voltage VSP. 10

Similar operations are performed with respect to the remaining DA converters 15. When an image data supplied to a DA converter 15 specifies the grayscale value “00h”, which corresponds to black, the data identification circuitry 18 associated with the DA converter 15 sets the data identification signal 25 outputted therefrom to “0”. This allows stopping the amplifying operation of the source amplifier 16 connected to the DA converter 15 which receives the image data specifying the grayscale value “00h”. When an image data supplied to a DA converter 15 does not specify the grayscale value “00h”, in contrast, the data identification circuitry 18 associated with the DA converter 15 sets the data identification signal 25 outputted therefrom to “1”. This allows the source amplifier 16 connected to the DA converter 15 to operate as a voltage follower, and output a drive voltage having the same voltage level as that of the grayscale voltage received from the DA converter 15. 15

This is followed by driving the B subpixels 8B connected to the selected gate line 6. In one embodiment, the control signal SW3 is activated to connect the source lines 7 connected to the B subpixels 8B are connected to the source outputs S₁ to S_(m/3). Furthermore, the RGB selectors 64 select the B latches 14B₁ to 14B_{m/3} of the output stage line latch circuitry 14 in response to the RGB select signal 65 and connect the B latches 14B₁ to 14B_{m/3} to the DA converters 15₁ to 15_{m/3}, respectively. The DA converters 15₁ to 15_{m/3} generate grayscale voltages corresponding to the grayscale values specified by the image data received from the B latches 14B₁ to 14B_{m/3}, and supply the generated grayscale voltages to the source amplifiers 16₁ to 16_{m/3}. 20

In the operation illustrated in FIG. 14, in which the image data supplied from the B latch 1462 to the DA converter 152 specifies the grayscale value “00h”, which corresponds to black, the data identification circuitry 182 sets the data identification signal 252 to “0”. The amplifier control circuitry 192 generates the individual amplifier control signals 272 so as to stop the amplifying operation of the source amplifiers 162. In other words, the amplifier turn-on signals AMPON_P and AMPON_N of the individual amplifier control signals 272, which are supplied to the source ampli- 25

fier 162, are deactivated. In FIG. 14, the waveform of the amplifier turn-on signal AMPON_P of the individual amplifier control signals 272 is indicated by the legend “AMPON_P(S2)”. 5

Additionally, depending on whether the display panel 1 operates in the normally black mode or the normally white mode, the amplifier control circuitries 192 activates one of the output control signals AMPOUTH_N and AMPOUTL_P of the individual amplifier control signals 272, and deactivates the other. When the display panel 1 operates in the normally black mode, the amplifier control circuitry 192 activates the output control signal AMPOUTH_N and deactivates the output control signal AMPOUTL_P. In response to the activation of the output control signal AMPOUTH_N, the source amplifier 162 sets the drive voltage to be supplied to S2 to the circuit ground level GND. When the display panel 1 operates in the normally white mode, the amplifier control circuitry 192 activates the output control signal AMPOUTL_P and deactivates the output control signal AMPOUTH_N. In response to the activation of the output control signal AMPOUTL_P, the source amplifier 162, which is configured to output a negative drive voltage, sets the drive voltage to be supplied to the source output S2 to the power supply voltage VSN. 10

Similar operations are performed with respect to the remaining DA converters 15. When an image data supplied to a DA converter 15 specifies the grayscale value “00h”, which corresponds to black, the data identification circuitry 18 associated with the DA converter 15 sets the data identification signal 25 outputted therefrom to “0”. This allows stopping the amplifying operation of the source amplifier 16 connected to the DA converter 15 which receives the image data specifying the grayscale value “00h”, which corresponds to black portions of the display panel. When an image data supplied to a DA converter 15 does not specify the grayscale value “00h”, in contrast, the data identification circuitry 18 associated with the DA converter 15 sets the data identification signal 25 outputted therefrom to “1”. This allows the source amplifier 16 connected to the DA converter 15 to operate as a voltage follower, and output a drive voltage having the same voltage level as that of the grayscale voltage received from the DA converter 15. 15

In parallel to the above-described operation in the N horizontal sync period, image data are sequentially transferred from the image data processing circuitry 12a to the initial stage line latch circuitry 13 via the line latch bus 20. The transferred image data are stored in the R latches 13R₁ to 13R_{m/3}, G latches 13G₁ to 13G_{m/3}, and B latches 13B₁ to 13B_{m/3} of the initial stage line latch circuitry 13. In one or more embodiments, in the Nth horizontal sync period, image data specifying the grayscale value “00h”, which corresponds to black, are transferred to the R latch 13R₁, G latch 13G₁, B latch 13B₁ and B latch 13B₂ of the initial stage line latch circuitry 13, and image data specifying grayscale values different from the grayscale value “00h” are transferred to the R latch 13R₂, G latch 13G₂. 20

In the (N+1)th horizontal sync period, pixel circuits 8 are driven in response to the image data which have been transferred to the initial stage line latch circuitry 13 in the Nth horizontal sync period. The pixel circuits 8 are driven in the (N+1)th horizontal sync period similarly to the Nth horizontal sync period, except for that the image data which have been transferred in the Nth horizontal sync period are used. Since the image data specifying the grayscale value “00h”, which corresponds to black portions of a display, have been transferred to the R latch 13R₁, G latch 13G₁ and 25

B latch $13B_1$ of the initial stage line latch circuitry 13 in the Nth horizontal sync period, the amplifying operation of the source amplifier 16_1 connected to the source output S_1 is stopped in the operation of the $(N+1)^{th}$ horizontal sync period, when drive voltages are supplied to the R subpixel $8R$, G subpixel $8G$ and B subpixel $8B$.

In one embodiment, for all of the associated R subpixel $8R$, G subpixel $8G$ and B subpixel $8B$, the data identification circuitry 18_1 sets to the data identification signal 25_1 to "0" and the amplifier control circuitry 19_1 generates the individual amplifier control signals 27_1 so as to stop the source amplifier 16_1 in response to the data identification signal 25_1 . In other words, the amplifier turn-on signals $AMPON\_P$ and $AMPON\_N$ of the individual amplifier control signals 27_1 supplied to the source amplifier 16_1 are deactivated. As described above, the amplifying operation of the source amplifier 16_1 is stopped when the amplifier turn-on signals $AMPON\_P$ and $AMPON\_N$ are deactivated.

In one or more embodiments, depending on whether the display panel 1 operates in the normally black mode or the normally white mode, the amplifier control circuitry 19_1 activates one of the output control signals $AMPOUTH\_N$ and $AMPOUTL\_P$ of the individual amplifier control signals 27_1 , and deactivates the other of the output control signals $AMPOUTH\_N$ and $AMPOUTL\_P$. When the display panel 1 operates in the normally black mode, the amplifier control circuitry 19_1 activates the output control signal $AMPOUTL\_P$ and deactivates the output control signal $AMPOUTH\_N$. In response to the activation of the output control signal $AMPOUTL\_P$, the source amplifier 16_1 sets the drive voltage outputted to the source output S_1 to the circuit ground level GND . When the display panel 1 operates in the normally white mode, on the other hand, the amplifier control circuitry 19_1 activates the output control signal $AMPOUTH\_N$ and deactivates the output control signal $AMPOUTL\_P$. In response to the activation of the output control signal $AMPOUTH\_N$, the source amplifier 16_1 sets the drive voltage outputted to the source output S_1 to the power supply voltage VSP .

Also in the operation illustrated in FIG. 14, the amplifying operation of a source amplifier 16 which supplies a drive voltage to a pixel circuit 8 that display black, when the drive voltage is written into the pixel circuit 8 . Additionally, the source amplifier 16 is configured to output the drive voltage corresponding to black when the amplifying operation thereof is stopped. This operation effectively reduces the power consumption while addressing the problem of the difference in the brightness level of "black".

The logic module 12 may be configured to identify whether or not each image data specifies the grayscale value corresponding to black, also in this embodiment.

FIG. 15 is a block diagram illustrating the configuration of the display driver $2A$, in which the logic module 12 is configured to identify whether or not each image data specifies the grayscale value "00h", which corresponds to black. In the configuration illustrated in FIG. 15, the data identification circuitries 18_1 to $18_{m/3}$ are removed and a data identification circuitry $12c$ is provided in the logic module 12 instead. The initial stage line latch circuitry 13 includes R latches $53R_1$ to $53R_{m/3}$, G latches $53G_1$ to $53G_{m/3}$ and B latches $53B_1$ to $53B_{m/3}$ to store data identification bits, and the output stage line latch circuitry 14 includes R latches $54R_1$ to $54R_{m/3}$, G latches $54G_1$ to $54G_{m/3}$ and B latches $54B_1$ to $54B_{m/3}$ to store data identification bits.

The data identification circuitry $12c$ is connected to the R latches $53R_1$ to $53R_{m/3}$, G latches $53G_1$ to $53G_{m/3}$ and B latches $53B_1$ to $53B_{m/3}$ of the initial stage line latch circuitry

13 via an amplifier control bus 51 and the R latches $53R_1$ to $53R_{m/3}$, G latches $53G_1$ to $53G_{m/3}$ and B latches $53B_1$ to $53B_{m/3}$ are connected to the R latches $54R_1$ to $54R_{m/3}$, G latches $54G_1$ to $54G_{m/3}$ and B latches $54B_1$ to $54B_{m/3}$ of the output stage line latch circuitry 14 , respectively.

The display driver $2A$ illustrated in FIG. 15 further includes RGB selectors 66_1 to $66_{m/3}$ which have outputs connected to the amplifier control circuitries 19_1 to $19_{m/3}$, respectively. Each RGB selector 66_k connects a selected one of the R latch $54R_k$, G latch $54G_k$ and B latch $54B_k$ of the output stage line latch circuitry 14 to the amplifier control circuitry 19_k in response to the RGB select signal 65 received from the display timing controller $12b$. The output signal of the one of the R latch $54R_k$, G latch $54G_k$ and B latch $54B_k$ selected by the RGB selector 66_k is supplied to the amplifier control circuitry 19_k as the data identification signal 25_k . The amplifier control circuitry 19_k generates the individual amplifier control signals 27_k in response to the data identification signal 25_k .

The display driver $2A$ configured as illustrated in FIG. 15 operates as follows. The data identification circuitry $12c$ identifies whether respective image data specify the grayscale value "00h", which corresponds to black, when the image data are sequentially transferred to the initial stage line latch circuitry 13 via the line latch bus 20 and outputs a data identification bit for each of the transferred image data. Each of the data identification bits is a one-bit data indicating whether the associated image data specifies the grayscale value "00h". The data identification bits are transferred to the initial stage line latch circuitry 13 via the amplifier control bus 51 and stored in the R latches $53R_1$ to $53R_{m/3}$, the G latches $53G_1$ to $53G_{m/3}$ and the B latches $53B_1$ to $53B_{m/3}$. The data identification bits which indicate whether the image data stored in the R latches $13R_1$ to $13R_{m/3}$ specify the grayscale value "00h" are stored in the R latches $53R_1$ to $53R_{m/3}$, respectively. Similarly, the data identification bits which indicate whether the image data stored in the G latches $13G_1$ to $13G_{m/3}$ specify the grayscale value "00h" are stored in the G latches $53G_1$ to $53G_{m/3}$, respectively, and the data identification bits which indicate whether the image data stored in the B latches $13B_1$ to $13B_{m/3}$ specify the grayscale value "00h" are stored in the B latches $53B_1$ to $53B_{m/3}$, respectively.

The data identification bits stored in the R latches $53R_1$ to $53R_{m/3}$, G latches $53G_1$ to $53G_{m/3}$ and B latches $53B_1$ to $53B_{m/3}$ are latched by the R latches $54R_1$ to $54R_{m/3}$, G latches $54G_1$ to $54G_{m/3}$ and B latches $54B_1$ to $54B_{m/3}$ of the output stage line latch circuitry 14 .

When R subpixels $8R$ are driven in each horizontal sync period, the control signal $SW1$ is activated. Additionally, in response to the RGB select signal 65 , the RGB selectors 64_1 to $64_{m/3}$ are set to select the R latches $14R_1$ to $14R_{m/3}$, respectively, and the RGB selectors 66_1 to $66_{m/3}$ are set to select the R latches $54R_1$ to $54R_{m/3}$.

The DA converters 15_1 to $15_{m/3}$ receive image data from the selected R latches $14R_1$ to $14R_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the output signals of the R latches $54R_1$ to $54R_{m/3}$, which are selected by the RGB selectors 66_1 to $66_{m/3}$, are supplied to the amplifier control circuitries 19_1 to $19_{m/3}$ as the data identification signals 25_1 to $25_{m/3}$. The amplifier control circuitries 19_1 to $19_{m/3}$ generate the individual amplifier control signals 27_1 to $27_{m/3}$.

in response to the data identification signals 25_1 to $25_{m/3}$. When the data identification signal 25_k is "0", that is, when the image data supplied to the DA converter 15_k specifies the grayscale value "00h", which corresponds to black, the amplifier control circuitry 19_k generates the individual amplifier control signals 27_k so as to stop the amplifying operation of the source amplifier 16_k . In other words, the amplifier turn-on signals AMPON_P and AMPON_N of the individual amplifier control signals 27_k supplied to the source amplifier 16_k are deactivated. As described above, the amplifying operation of the source amplifier 16_k is stopped when the amplifier turn-on signals AMPON_P and AMPON_N are deactivated.

In one or more embodiments, depending on whether the display panel 1A operates in the normally black mode or the normally white mode, the amplifier control circuitries 19_k activates one of the output control signals AMPOUTH_N and AMPOUTL_P of the individual amplifier control signals 27_k , and deactivates the other. When the display panel 1A operates in the normally black mode, the amplifier control circuitry 19_k outputs the output control signals AMPOUTH_N and AMPOUTL_P so that the drive voltage supplied from the source amplifier 16_k to the source outputs Sk is set to the circuit ground level GND. When the display panel 1A operates in the normally white mode, on the other hand, the amplifier control circuitry 19_k , if the source amplifier 16_k is configured to output a positive drive voltage, outputs the output control signals AMPOUTH_N and AMPOUTL_P so that the drive voltage supplied to the source output Sk is set to the power supply voltage VSP, and if the source amplifier 16_k is configured to output a negative drive voltage, the amplifier control circuitry 19_k outputs the output control signals AMPOUTH_N and AMPOUTL_P so that the drive voltage supplied to the source output Sk is set to the power supply voltage VSN.

The G subpixels 8G are driven similarly to the R subpixels 8R in each horizontal sync period, except for that the control signal SW2 is activated, the RGB selectors 64_1 to $64_{m/3}$ respectively select the G latches $14G_1$ to $14G_{m/3}$ in response to the RGB select signal 65, and the RGB selectors 66_1 to $66_{m/3}$ respectively select the G latches $54G_1$ to $54G_{m/3}$ in response to the RGB select signal 65.

The DA converters 15_1 to $15_{m/3}$ receive image data from the selected G latches $14G_1$ to $14G_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the output signals of the G latches $54G_1$ to $54G_{m/3}$, which are selected by the RGB selectors 66_1 to $66_{m/3}$, are supplied to the amplifier control circuitries 19_1 to $19_{m/3}$ as the data identification signals 25_1 to $25_{m/3}$. The amplifier control circuitries 19_1 to $19_{m/3}$ generate the individual amplifier control signals 27_1 to $27_{m/3}$ in response to the data identification signals 25_1 to $25_{m/3}$. When the data identification signal 25_k is "0", the amplifier control circuitry 19_k generates the individual amplifier control signals 27_k so as to stop the amplifying operation of the source amplifier 16_k .

In one or more embodiments, depending on whether the display panel 1A operates in the normally black mode or the normally white mode, the amplifier control circuitries 19_k activates one of the output control signals AMPOUTH_N and AMPOUTL_P of the individual amplifier control signals 27_k , and deactivates the other.

Furthermore, the B subpixels 8B are driven similarly to the R subpixels 8R and G subpixels 8G in each horizontal sync period, except for that the control signal SW3 is activated, the RGB selectors 64_1 to $64_{m/3}$ respectively select the B latches $14B_1$ to $14B_{m/3}$ in response to the RGB select signal 65, and the RGB selectors 66_1 to $66_{m/3}$ respectively select the B latches $54B_1$ to $54B_{m/3}$ in response to the RGB select signal 65.

The DA converters 15_1 to $15_{m/3}$ receive image data from the selected B latches $14B_1$ to $14B_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the output signals of the B latches $54B_1$ to $54B_{m/3}$, which are selected by the RGB selectors 66_1 to $66_{m/3}$, are supplied to the amplifier control circuitries 19_1 to $19_{m/3}$ as the data identification signals 25_1 to $25_{m/3}$. The amplifier control circuitries 19_1 to $19_{m/3}$ generate the individual amplifier control signals 27_1 to $27_{m/3}$ in response to the data identification signals 25_1 to $25_{m/3}$. When the data identification signal 25_k is "0", the amplifier control circuitry 19_k generates the individual amplifier control signals 27_k so as to stop the amplifying operation of the source amplifier 16_k .

In one or more embodiments, depending on whether the display panel 1A operates in the normally black mode or the normally white mode, the amplifier control circuitry 19_k activates one of the output control signals AMPOUTH_N and AMPOUTL_P of the individual amplifier control signals 27_k , and deactivates the other.

Also in the display driver 2A illustrated in FIG. 15, the amplifying operation of a source amplifier 16 which supplies a drive voltage to a pixel circuit 8 that display black, when the drive voltage is written into the pixel circuit 8. Additionally, the source amplifier 16 is configured to output the drive voltage corresponding to black when the amplifying operation thereof is stopped. This operation effectively reduces the power consumption, depending on the display image.

FIG. 16 is a block diagram illustrating the configuration of the display driver 2B according to one or more embodiments. In one or more embodiments, the display driver 2B is configured similarly to the display driver 2 of FIG. 2, and adapted to drive the display panel 1 illustrated in FIG. 2. The difference is as follows.

In one or more embodiments, the display driver 2B is configured to supply common amplifier control signals 27_{COM} to all of the source amplifiers 16_1 to 16_m and the execution and stop of the amplifying operations of the source amplifiers 16_1 to 16_m are controlled. In this embodiment, those configured to output a positive drive voltage out of the source amplifiers 16_1 to 16_m are configured as illustrated in FIG. 7A and those configured to output a negative drive voltage out of the source amplifiers 16_1 to 16_m are configured as illustrated in FIG. 7B. In such an embodiment, the common amplifier control signals 27_{COM} include the amplifier turn-on signal AMPON_P and AMPON_N and the output control signals AMPOUTH_N and AMPOUTL_P.

Additionally, the logic module 12 is configured to identify whether all of the image data supplied to the DA converters 15_1 to 15_m specify the grayscale value "00h", which corresponds to black, in each horizontal sync period, to generate the common amplifier control signals 27_{COM} .

In one embodiment, the logic module 12 includes a data identification circuitry 12d, a latch 12e and an amplifier control circuitry 12f. The data identification circuitry 12d is configured to identify whether each of image data sequentially transferred from the image data processing circuitry 12a to the latches 13₁ to 13_m of the initial stage line latch circuitry 13 specifies the grayscale value “00h”, which corresponds to black, and sequentially output data identification bits. The latch 12e stores therein the data identification bits received from the data identification circuitry 12d.

The amplifier control circuitry 12f generates the common amplifier control signals 27_{COM} in response to the data identification bits stored in the latch 12e and the amplifier control signal 26 received from the display timing controller 12b. The amplifier control signal 26 received from the display timing controller 12b is used to totally stop the amplifying operations of all of the source amplifiers 16₁ to 16_m.

When the amplifying operations of all of the source amplifiers 16₁ to 16_m are stopped at the same time for some reason, the display timing controller 12b deactivates the amplifier control signal 26. In such an embodiment, the amplifier control circuitry 12f generates the common amplifier control signals 27_{COM} so as to stop the amplifying operations of all of the source amplifiers 16₁ to 16_m, independently of the data identification bits received from the data identification circuitry 12d.

When the display panel 1 is driven to display an image, the display timing controller 12b activates the amplifier control signal 26. In such an embodiment, the amplifier control circuitry 12f generates the common amplifier control signals 27_{COM} in response to the data identification bits stored in the latch 12e, to thereby control the execution and stop of the amplifying operations of the source amplifiers 16₁ to 16_m. The amplifier control circuitry 12f determines whether all of the image data supplied to the DA converters 15₁ to 15, specify the grayscale value “00h”, which corresponds to black, in each horizontal sync period.

When at least one of the image data supplied to the DA converters 15₁ to 15, does not specify the grayscale value “00h”, the amplifier control circuitry 12f generates the common amplifier control signals 27_{COM} so as to allow all of the source amplifiers 16₁ to 16_m to perform the amplifying operations. The amplifier control circuitry 12f activates the amplifier turn-on signals AMPON_P and AMPON_N of the common amplifier control signals 27_{COM}.

When all of the image data supplied to the DA converters 15₁ to 15_m specify the grayscale value “00h”, the amplifier control circuitry 12f generates the common amplifier control signals 27_{COM} so as to stop the amplifying operations of all of the source amplifiers 16₁ to 16_m. To stop the amplifying operations of the source amplifiers 16₁ to 16_m, the amplifier control circuitry 12f deactivates the amplifier turn-on signals AMPON_P and AMPON_N of the common amplifier control signals 27_{COM}.

Additionally, depending on whether the display panel 1 operates in the normally black mode or the normally white mode, the amplifier control circuitry 12f activates one of the output control signals AMPOUTH_N and AMPOUTL_P of the common amplifier control signals 27_{COM}, and deactivates the other. When the display panel 1 operates in the normally black mode, the amplifier control circuitry 12f outputs the output control signals AMPOUTH_N and AMPOUTL_P so that the drive voltages outputted from the source amplifier 16₁ to 16_m are set to the circuit ground level GND. When the display panel 1 operates in the normally white mode, the amplifier control circuitry 12f outputs the

output control signals AMPOUTH_N and AMPOUTL_P so that the drive voltages outputted from ones of the source amplifier 16₁ to 16_m, configured to output positive drive voltages are set to the power supply voltage VSP, and the drive voltages outputted from ones of the source amplifier 16₁ to 16_m, configured to output negative drive voltages are set to the power supply voltage VSN.

FIG. 17 schematically illustrates the correspondence between an image displayed by the display device incorporating the display driver 2B of this embodiment and the waveforms of the amplifier turn-on signal AMPON_P supplied to the source amplifiers 16. For easiness of understanding, the operation of the display device 100 is illustrated under an assumption that the number m of the source outputs, that is, the number of the source amplifiers 16, is 20. In the example illustrated in FIG. 17, the image displayed on the display panel 1 includes characters “12:12”.

The upper part of FIG. 17 illustrates the association of the image and the source outputs S₁ to S₂₀, that is, the pixel circuits 8 of the display panel 1 and the source outputs S₁ to S₂₀. The lower part of FIG. 17 illustrates the state of the amplifier turn-on signal AMPON_P supplied to the source amplifiers 16 at the timing when the respective pixel circuits 8 of the display panel 1 are driven. In FIG. 17, the waveform of the amplifier turn-on signal AMPON_P of the common amplifier control signals 27_{COM} is illustrated under an assumption that the pixel circuits 8 are sequentially driven from left to right of the image. The legend “1H” in FIG. 17 represents one horizontal sync period.

In the first to third horizontal sync periods, in which all of the selected pixel circuits 8 display black, the amplifier turn-on signal AMPON_P of the common amplifier control signals 27_{COM} is deactivated to stop the amplifying operations of all of the source amplifiers 16.

In the fourth horizontal sync period, in which pixel circuits 8 connected to the source outputs S₁₄ to S₁₈ do not display black, the amplifier turn-on signal AMPON_P of the common amplifier control signals 27_{COM} is activated to allow the amplifying operations of all of the source amplifiers 16.

In the fifth horizontal sync periods, in which all of the selected pixel circuits 8 display black, the amplifier turn-on signal AMPON_P of the common amplifier control signals 27_{COM} is deactivated to stop the amplifying operations of all of the source amplifiers 16.

Subsequently, a similar operation is performed to display the image including the characters “12:12”.

As described above, the display device 100 of this embodiment is configured so that the amplifying operations of all of the source amplifiers 16 are stopped in a horizontal sync period, when all of the selected pixel circuits 8 display black in the horizontal sync period. Additionally, in the display device 100 of this embodiment, the source amplifiers 16₁ to 16_m are each configured to output the drive voltage corresponding to black when the amplifying operation thereof is stopped. In this embodiment, “black” displayed on the display panel 1 includes “black” displayed in the state in which the corresponding source amplifier is operated and “black” displayed in the state in which the amplifying operation of the corresponding source amplifier is stopped. To address this, the source amplifiers are configured to output the power supply voltage (VSP or VSN) or the circuit ground level (GND) corresponding to black portions of the display panel, even when the source amplifiers are operated. This operation effectively reduces the power consumption, while addressing the above-described problem of the difference in the brightness level of “black”.

In this embodiment, in which the common amplifier control signals 27_{COM} are supplied to all of the source amplifiers 16_1 to $16_{m/3}$ to control the execution and stop of the amplifying operations of the source amplifiers 16_1 to $16_{m/3}$, a time-divisional drive scheme may be implemented. FIG. 18 is a block diagram illustrating the configuration of the display driver 2B in this case. Illustrated in FIG. 18 is the configuration of circuitry related to the operation of outputting drive voltages from two source outputs S1 and S2 in the display driver 2B. When a time-divisional drive scheme is implemented, the display panel 1A illustrated in FIG. 12A may be used for example.

The display driver 2B illustrated in FIG. 18 is configured similarly to the display driver 2A illustrated in FIG. 13. The number of the source outputs is $m/3$ also in the display driver 2B illustrated in FIG. 18, and accordingly the numbers of the DA converters 15 and the source amplifiers 16 are $m/3$ and the number of output switch circuitries 17 is $m/6$.

In the display driver 2B illustrated in FIG. 18, the initial stage line latch circuitry 13 includes R latches $13R_1$ to $13R_{m/3}$, G latches $13G_1$ to $13G_{m/3}$ and B latches $13B_1$ to $13B_{m/3}$. Similarly, the output stage line latch circuitry 14 includes R latches $14R_1$ to $14R_{m/3}$, G latches $14G_1$ to $14G_{m/3}$ and B latches $14B_1$ to $14B_{m/3}$. Illustrated in FIG. 18 are two of the R latches $13R_1$ to $13R_{m/3}$, two of the G latches $13G_1$ to $13G_{m/3}$, two of the B latches $13B_1$ to $13B_{m/3}$, two of the R latches $14R_1$ to $14R_{m/3}$, two of the G latches $14G_1$ to $14G_{m/3}$ and two of the B latches $14B_1$ to $14B_{m/3}$.

Additionally, the display driver 2B includes RGB selectors 64_1 to $64_{m/3}$. Each RGB selector 64_k connects a selected one of the R latch $14R_k$, G latch $14G_k$ and B latch $14B_k$ of the output stage line latch circuitry 14 to the DA converter 15_k in response to a RGB select signal 65 received from the display timing controller 12_b. The image data stored in the latch selected by the RGB selector 64_k is supplied to the DA converter 15_k .

The display driver 2B illustrated in FIG. 18 operates as follows. When image data are sequentially transferred to the initial stage line latch circuitry 13 via the line latch bus 20, the data identification circuitry 12_d identifies whether each of image data specifies the grayscale value “00h”, which corresponds to black, and to output a data identification bit for each of the image data. Each data identification bit is a one-bit data indicative of whether or not the corresponding image data specifies the grayscale value “00h”. The data identification bits are stored in the latch 12_e.

When R subpixels 8R are driven in each horizontal sync period, the control signal SW1 is activated and the RGB selectors 64_1 to $64_{m/3}$ select the R latches $14R_1$ to $14R_{m/3}$ in response to the RGB select signal 65.

The DA converters 15_1 to $15_{m/3}$ receive image data from the selected R latches $14R_1$ to $14R_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the amplifier control circuitry 12_f identifies whether or not all of the image data supplied from the R latches $14R_1$ to $14R_{m/3}$ to the DA converters 15_1 to $15_{m/3}$ specify the grayscale value “00h”, which corresponds to black, on the basis of the data identification bits stored in the latch 12_e. When all of the image data supplied to the DA converters 15_1 to $15_{m/3}$ specify the grayscale value “00h”, the amplifier control circuitry 12_f generates the common amplifier control signals 27_{COM} so as to stop the amplifying operations of all of the source

amplifiers 16_1 to $16_{m/3}$. In other words, the amplifier turn-on signals AMPON_P and AMPON_N of the common amplifier control signals 27_{COM} supplied to the source amplifiers 16_1 to $16_{m/3}$ are deactivated. As described above, the amplifying operations of the source amplifiers 16_1 to $16_{m/3}$ are stopped when the amplifier turn-on signals AMPON_P and AMPON_N are deactivated.

In one or more embodiments, depending on whether the display panel 1 operates in the normally black mode or the normally white mode, the amplifier control circuitry 12_f activates one of the output control signals AMPOUTH_N and AMPOUTL_P of the common amplifier control signals 27_{COM} and deactivates the other. When the display panel 1 operates in the normally black mode, the amplifier control circuitry 12_f outputs the output control signals AMPOUTH_N and AMPOUTL_P so that the drive voltages outputted from the source amplifier 16_1 to $16_{m/3}$ are set to the circuit ground level GND. When the display panel 1 operates in the normally white mode, the amplifier control circuitry 12_f outputs the output control signals AMPOUTH_N and AMPOUTL_P so that the drive voltages outputted from ones of the source amplifier 16_1 to $16_{m/3}$ configured to output positive drive voltages are set to the power supply voltage VSP, and the drive voltages outputted from ones of the source amplifier 16_1 to $16_{m/3}$ configured to output negative drive voltages are set to the power supply voltage VSN.

The G subpixels 8G are driven similarly to the R subpixels 8R in each horizontal sync period, except for that the control signal SW2 is activated, and the RGB selectors 64_1 to $64_{m/3}$ respectively select the G latches $14G_1$ to $14G_{m/3}$ in response to the RGB select signal 65.

The DA converters 15_1 to $15_{m/3}$ receive image data from the selected G latches $14G_1$ to $14G_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the amplifier control circuitry 12_f identifies whether or not all of the image data supplied from the G latches $14G_1$ to $14G_{m/3}$ to the DA converters 15_1 to $15_{m/3}$ specify the grayscale value “00h”, which corresponds to black, on the basis of the data identification bits stored in the latch 12_e. When all of the image data supplied to the DA converters 15_1 to $15_{m/3}$ specify the grayscale value “00h”, the amplifier control circuitry 12_f generates the common amplifier control signals 27_{COM} so as to stop the amplifying operations of all of the source amplifiers 16_1 to $16_{m/3}$. In other words, the amplifier turn-on signals AMPON_P and AMPON_N of the common amplifier control signals 27_{COM} supplied to the source amplifiers 16_1 to $16_{m/3}$ are deactivated. As described above, the amplifying operations of the source amplifiers 16_1 to $16_{m/3}$ are stopped when the amplifier turn-on signals AMPON_P and AMPON_N are deactivated.

In one or more embodiments, depending on whether the display panel 1 operates in the normally black mode or the normally white mode, the amplifier control circuitry 12_f activates one of the output control signals AMPOUTH_N and AMPOUTL_P of the common amplifier control signals 27_{COM} and deactivates the other.

The B subpixels 8B are driven similarly to the R subpixels 8R and G subpixels 8G in each horizontal sync period, except for that the control signal SW3 is activated, and the RGB selectors 64_1 to $64_{m/3}$ respectively select the B latches $14B_1$ to $14B_{m/3}$ in response to the RGB select signal 65.

The DA converters 15_1 to $15_{m/3}$ receive image data from the selected B latches $14B_1$ to $14B_{m/3}$, generate grayscale voltages corresponding to the grayscale values specified by the received image data and supply the grayscale voltages to the source amplifiers 16_1 to $16_{m/3}$. The source amplifiers 16_1 to $16_{m/3}$ output drive voltages corresponding to the grayscale voltages received from the DA converters 15_1 to $15_{m/3}$.

In one or more embodiments, the amplifier control circuitry $12f$ identifies whether or not all of the image data supplied from the B latches $14B_1$ to $14B_{m/3}$ to the DA converters 15_1 to $15_{m/3}$ specify the grayscale value “00h”, which corresponds to black, on the basis of the data identification bits stored in the latch $12e$. When all of the image data supplied to the DA converters 15_1 to $15_{m/3}$ specify the grayscale value “00h”, the amplifier control circuitry $12f$ generates the common amplifier control signals 27_{COM} so as to stop the amplifying operations of all of the source amplifiers 16_1 to $16_{m/3}$. In other words, the amplifier turn-on signals AMPON_P and AMPON_N of the common amplifier control signals 27_{COM} supplied to the source amplifiers 16_1 to $16_{m/3}$ are deactivated. As described above, the amplifying operations of the source amplifiers 16_1 to $16_{m/3}$ are stopped when the amplifier turn-on signals AMPON_P and AMPON_N are deactivated.

As described above, in the configuration illustrated in FIG. 18, when all of the image data supplied from the R latches $14R_1$ to $14R_{m/3}$ to the DA converters 15_1 to $15_{m/3}$ specify the grayscale value “00h”, which corresponds to black, in a horizontal sync period, the amplifying operations of all of the source amplifiers 16_1 to 16_m are stopped in driving R subpixels $8R$ selected in the horizontal sync period. Similarly, when all of the image data supplied from the G latches $14G_1$ to $14G_{m/3}$ to the DA converters 15_1 to $15_{m/3}$ specify the grayscale value “00h” in a horizontal sync period, the amplifying operations of all of the source amplifiers 16_1 to 16_m are stopped in driving G subpixels $8G$ selected in the horizontal sync period. Furthermore, when all of the image data supplied from the B latches $14B_1$ to $14B_{m/3}$ to the DA converters 15_1 to $15_{m/3}$ specify the grayscale value “00h” in a horizontal sync period, the amplifying operations of all of the source amplifiers 16_1 to 16_m are stopped in driving B subpixels $8B$ selected in the horizontal sync period. Additionally, in the display device 100 of this embodiment, the source amplifiers 16_1 to 16_m are each configured to output the drive voltage corresponding to black portions of the display when the amplifying operation thereof is stopped. The source amplifiers are configured to output the power supply voltage (VSP or VSN) or the circuit ground level (GND) to display black even when the source amplifiers are operated, similarly to the case when the amplifying operations of the source amplifiers are stopped. This operation effectively reduces the power consumption, while addressing the above-described problem of the difference in the brightness level of “black”.

In one or more embodiments, the display device is configured similarly to the display device 100 as illustrated in FIG. 2. In one embodiment, an OLED (organic light emitting diode) display panel is used as the display panel 1 .

FIGS. 19A and 19B are circuit diagrams illustrating examples of the configuration of the pixel circuits 8 when an OLED display panel is used as the display panel 1 . The pixel circuit 8 illustrated in FIG. 19A, which incorporates an NMOS transistor as a drive transistor, is hereinafter referred to as NMOS pixel circuit $8N$.

The NMOS pixel circuit $8N$ includes a select transistor $71N$, an OLED element 72 , a drive transistor $73N$ and a storage capacitor 74 . NMOS TFTs (thin film transistors) are

used for both of the select transistor $71N$ and the drive transistor $73N$. The select transistor $71N$ has a source connected to a source line 7 , a drain connected to the gate of the drive transistor $73N$ and a gate connected to a gate line 5 . The OLED element 72 has an anode connected to a power line 75 and a cathode connected to the drain of the drive transistor $73N$. The power line 75 is supplied with a power supply voltage ELVDD. The drive transistor $73N$ has a drain connected to the cathode of the OLED element 72 , a source connected to a ground line 76 and a gate connected to the drain of the select transistor $71N$. The ground line 76 is supplied with the circuit ground level GND. The storage capacitor 74 is connected between the gate and source of the drive transistor $73N$. The drive voltage written in the NMOS pixel circuit $8N$ is held across the storage capacitor 74 .

The pixel circuit 8 illustrated in FIG. 19B, which incorporates a PMOS transistor as a drive transistor, is hereinafter referred to as PMOS pixel circuit $8P$.

The PMOS pixel circuit $8P$ includes a select transistor $71P$, an OLED element 72 , a drive transistor $73P$ and a storage capacitor 74 . PMOS TFTs are used as the select transistor $71P$ and the drive transistor $73P$. The select transistor $71P$ has a source connected to a source line 7 , a drain connected to the gate of the drive transistor $73P$ and a gate connected to a gate line 6 . The OLED element 72 has an anode connected to the drain of the drive transistor $73P$ and a cathode connected to a ground line 76 . The drive transistor $73P$ has a source connected to a power line 75 , a drain connected to the cathode of the OLED element 72 and a gate connected to the drain of the select transistor $71P$. The storage capacitor 74 is connected between the gate and source of the drive transistor $73P$. The drive voltage written into the PMOS pixel circuit $8P$ is held across the storage capacitor 74 .

FIG. 20 is a block diagram illustrating a display driver $2C$ used to drive the OLED display panel in this embodiment. The display driver $2C$ of this embodiment is configured similarly to the display driver 2 of the embodiment illustrated in FIG. 5. The inversion drive is not performed in driving the OLED display panel, and therefore the output switch circuitries 17_1 to $17_{m/2}$ are removed; the source amplifiers 16_1 to 16_m are connected to the source outputs S_1 to S_m , respectively. All the DA converters 15_1 to 15_m are configured to output positive grayscale voltages and all the source amplifiers 16_1 to 16_m are configured to output positive drive voltages. The source amplifiers 16_1 to 16_m may be configured as illustrated in FIG. 7A, for example. In such an embodiment, the power supply voltage ELVDD is supplied in place of the power supply voltage VSP.

FIG. 21A illustrates a table indicating the correspondence relationship between the grayscale values specified by image data and the grayscale voltages outputted from the DA converters 15 for the case when the NMOS pixel circuits $8N$ are used in this embodiment, that is, the drive voltages to be written into the NMOS pixel circuits $8N$. When NMOS pixel circuits $8N$ are used, the grayscale voltage corresponding to the grayscale value “00h”, which corresponds to black, is set to the circuit ground level GND. The voltage levels of the respective grayscale voltages are defined so that the voltage levels of the grayscale voltages are increased as the grayscale values specified by image data are increased.

FIG. 21B illustrates a table indicating the correspondence relationship between the grayscale values specified by image data and the grayscale voltages outputted from the DA converters 15 for the case when the PMOS pixel circuits $8P$ are used in this embodiment, that is, the drive voltages to be written into the PMOS pixel circuits $8P$. When PMOS pixel

circuits 8P are used, the grayscale voltage corresponding to the grayscale value “00h”, which corresponds to black, is set to the power supply voltage ELVDD, which is supplied to the power line 75 of each PMOS pixel circuit 8P of the OLED display panel. The voltage levels of the respective grayscale voltages are defined so that the voltage levels of the grayscale voltages are decreased as the grayscale values specified by image data are increased.

The display driver 2C illustrated in FIG. 20 operates similarly to the display driver 2 illustrated in FIG. 5, except for that all of the DA converters 15₁ to 15_m output positive grayscale voltages, and all of the source amplifiers 16₁ to 16_m output positive drive voltages.

Also in this embodiment, the amplifying operation of a source amplifier 16 that supplies a drive voltage to a pixel circuit 8 which displays black is stopped, when the drive voltage is written into the pixel circuit 8. The stopping of the amplifying operation is achieved by stopping the operations of current sources included in the source amplifier 16, in this embodiment, the constant current sources 38, 39 and the floating current sources 45 and 46. This operation effectively reduces the power consumption when portions of the display are black.

Additionally, the source amplifier 16 is configured to output the drive voltage corresponding to black, when the amplifying operation of the source amplifier 16 is stopped. When NMOS pixel circuits 8N are used, the drive voltage corresponding to black is the circuit ground level GND, and, In such an embodiment, the source amplifier 16 outputs the circuit ground level GND when the amplifying operation thereof is stopped. When PMOS pixel circuits 8P are used, the drive voltage corresponding to black portions of the display panel is the power supply voltage ELVDD, and, In such an embodiment, the source amplifier 16 outputs the power supply voltage ELVDD when the amplifying operation thereof is stopped.

Also in this embodiment, the logic module 12 may be configured to identify whether each of the image data supplied to the DA converters 15 specifies the grayscale value corresponding to black, instead of providing the data identification circuitries 18 which identifies whether each image data specifies the grayscale value corresponding to black, similarly to the display driver 2 illustrated in FIG. 10.

FIG. 22 is a block diagram illustrating the display driver 2C thus configured. The display driver 2C illustrated in FIG. 22 is configured similarly to the display driver 2 illustrated in FIG. 10. The output switch circuitries 17₁ to 17_{m/2} are removed and the source amplifiers 16₁ to 16_m are connected to the source outputs S₁ to S_m, respectively. All the DA converters 15₁ to 15_m are configured to output positive grayscale voltages and all the source amplifiers 16₁ to 16_m are configured to output positive drive voltages. The source amplifiers 16₁ to 16_m may be configured as illustrated in FIG. 7A, for example. In such an embodiment, the power supply voltage ELVDD is supplied in place of the power supply voltage VSP.

The display driver 2C illustrated in FIG. 22 operates similarly to the display driver 2 illustrated in FIG. 10, except for that all of the DA converters 15₁ to 15_m output positive grayscale voltages, and all of the source amplifiers 16₁ to 16_m output positive drive voltages.

Also in this embodiment, the common amplifier control signals 27_{COM} may be supplied to all of the source amplifiers 16₁ to 16_m to control the execution and stop of the amplifying operations of the source amplifiers 16₁ to 16_m, similarly to the display driver 2B illustrated in FIG. 16.

FIG. 23 is a block diagram illustrating the display driver 2C thus configured. The display driver 2C illustrated in FIG. 23 is configured similarly to the display driver 2 illustrated in FIG. 16. The output switch circuitries 17₁ to 17_{m/2} are removed and the source amplifiers 16₁ to 16_m are connected to the source outputs S₁ to S_m, respectively. All of the DA converters 15₁ to 15_m are configured to output positive grayscale voltages and all of the source amplifiers 16₁ to 16_m are configured to output positive drive voltages. The source amplifiers 16₁ to 16_m may be configured as illustrated in FIG. 7A, for example. In such an embodiment, the power supply voltage ELVDD is supplied in place of the power supply voltage VSP.

The display driver 2C illustrated in FIG. 23 operates similarly to the display driver 2B illustrated in FIG. 16, except for that all of the DA converters 15₁ to 15_m output positive grayscale voltages, and all of the source amplifiers 16₁ to 16_m output positive drive voltages.

Although embodiments of the present disclosure have been specifically described in the above, a person skilled in the art would appreciate that the technologies disclosed in the present disclosure may be implemented with various modifications. It should be also noted that the above-described embodiments may be combined in an actual implementation as long as no technological inconsistency occurs.

What is claimed is:

1. A display driver comprising:
a plurality of source amplifiers, each of the plurality of source amplifiers configured to drive an associated one of a plurality of source lines of a display panel with a first drive voltage corresponding to a grayscale value specified by associated image data; and
an amplifier control system comprising:

data identification circuitries, each of the data identification circuitries paired with a respective one of the plurality of source amplifiers, each of the data identification circuitries configured to process the image data associated with the paired source amplifier; and
amplifier control circuitries, each of the amplifier control circuitries paired with a respective one of the data identification circuitries, each of the amplifier control circuitries configured to control execution and stop of an amplifying operation of the paired source amplifier based on the processed image data received from the paired data identification circuitry.

2. The display driver according to claim 1, wherein each of the plurality of source amplifiers comprises a current source configured to generate a bias current, the first drive voltage is based on the bias current, and

wherein, in response to stopping the amplifying operation thereof, each of the plurality of source amplifiers is configured to:
stop generating the bias current with the current source; and
output the first drive voltage corresponding to a grayscale value corresponding to black portions of the display panel.

3. The display driver according to claim 1, wherein each of the amplifier control circuitries is further configured to:
stop the amplifying operation of the paired source amplifier in response to the image data associated with the paired source amplifier specifying a grayscale value corresponding to a black portion of the display panel.

4. The display driver according to claim 1, wherein each of the amplifier control circuitries is further configured to:
stop the amplifying operation of paired source amplifier in response to the image data associated with the paired

source amplifier specifying a grayscale value corresponding to a black portion of the display panel; and execute the amplifying operation of the paired source amplifier in response to the image data associated with the paired source amplifier not specifying the grayscale value corresponding to the black portion of the display panel.

5. The display driver according to claim 1, wherein the display driver further comprises: first digital to analog (DA) converters configured to: 10 respectively receive image data associated with the plurality of source amplifiers; and respectively output grayscale voltages corresponding to grayscale values specified by the received image data, and 15 wherein each of the plurality of source amplifiers is connected to a respective one of the DA converters, and is configured to output the first drive voltage in response to the grayscale voltages received from the 20 respective one of the DA converters.
6. The display driver according to claim 5, wherein the each of data identification circuitries is paired with a respective one of the DA converters, and 25 wherein processing the image data comprises identifying whether the image data supplied to the paired DA converter specifies the grayscale value corresponding to a black portion of the display panel.
7. The display driver according to claim 1, wherein the display driver further comprises: 30 a line latch bus; an amplifier control bus; a line latch circuitry comprising latches configured to respectively receive the image data associated with the plurality of source amplifiers via the line latch bus; and 35 digital to analog (DA) converters configured to output grayscale voltages corresponding to grayscale values specified by the image data received from the latches, 40 wherein the plurality of source amplifiers is connected to respective ones of the DA converters, and configured to output the first drive voltages in response to the grayscale voltages received from the respective ones of the DA converters, 45 wherein the data identification circuitries are configured to supply, to the line latch circuitry, data identification bits indicating whether the image data associated with the plurality of source amplifiers specifies the grayscale value corresponding to black portions of the display panel, via the amplifier control bus, 50 wherein the line latch circuitry further comprises data identification bit latches configured to store respective ones of the data identification bits, and 55 wherein each of the amplifier control circuitries is configured to control execution and stop of the amplifying operation of the paired source amplifier in response to the data identification bits stored in the data identification bit latches.
8. The display driver according to claim 1, wherein each of the amplifier control circuitries is further configured to: 60 stop amplifying operations of the paired source amplifier in a corresponding horizontal sync period in response to all of the image data associated with the plurality of source amplifiers specifying grayscale values corresponding to black portions of the display driver in a specific horizontal sync period. 65

9. The display driver according to claim 1, wherein the display panel includes a liquid crystal display panel configured to operate in a normally black mode, and wherein a voltage level of a second drive voltage corresponding to black portions of the display panel is a circuit ground level of the display driver.

10. The display driver according to claim 1, wherein the display panel includes a liquid crystal display panel configured to operate in a normally white mode, 10 wherein the plurality of source amplifiers comprises: a positive side source amplifier configured to output a positive drive voltage with respect to a circuit ground of the display driver; and a negative side source amplifier configured to output a negative drive voltage with respect to the circuit ground of the display driver, wherein a second drive voltage corresponding to black portions of the display panel with respect to the positive side source amplifier is a first power supply voltage supplied to the positive side source amplifier, the first power supply voltage being positive with respect to the circuit ground of the display driver, and wherein the second drive voltage corresponding to black portions of the display panel with respect to the positive side source amplifier is a second power supply voltage supplied to the negative side source amplifier, the second power supply voltage being negative with respect to the circuit ground of the display driver.
11. The display driver according to claim 1, wherein the display panel comprises an organic light emitting diode (OLED) display panel comprising a plurality of NMOS pixel circuits connected to the plurality of source lines, 30 wherein each of the plurality of NMOS pixel circuits comprises: a drive transistor configured as an NMOS transistor; an OLED element; and a storage capacitor connected between a gate and source of the drive transistor, a drive voltage outputted from an associated one of the plurality of source amplifiers being written into the storage capacitor, 40 wherein the drive transistor and the OLED element are connected in series between a power line supplied with a power supply voltage and a ground line supplied with a circuit ground level of the display driver, and wherein a second drive voltage corresponding to black portions of the display panel is the circuit ground level of the display driver.
12. The display driver according to claim 1, wherein the display panel comprises an organic light emitting diode (OLED) display panel comprising a plurality of PMOS pixel circuits connected to the plurality of source lines, 50 wherein each of the plurality of PMOS pixel circuits comprises: a drive transistor configured as a PMOS transistor; an OLED element; and a storage capacitor connected between a gate and source of the drive transistor and configured to store the first drive voltage outputted from an associated one of the plurality of source amplifiers, 55 wherein the drive transistor and the OLED element is connected in series between a power line supplied with a power supply voltage and a ground line supplied with a circuit ground level of the display driver, and wherein a second drive voltage corresponding to black portions of the display panel is the power supply voltage. 65

41

13. A display device comprising:
 a display panel comprising a plurality of source lines; and
 a display driver comprising:
 a plurality of source amplifiers, wherein each of the plurality of source amplifiers is configured to:
 drive an associated one of the source lines with a first drive voltage corresponding to a grayscale value specified by associated image data; and
 an amplifier control system comprising:
 data identification circuitries, each of the data identification circuitries paired with a respective one of the plurality of source amplifiers, each of the data identification circuitries configured to process the image data associated with the paired source amplifier; and
 15 amplifier control circuitries, each of the amplifier control circuitries paired with a respective one of the data identification circuitries, each of the amplifier control circuitries configured to control execution and stop of an amplifying operation of the paired source amplifier based on the processed image data received from the paired data identification circuitry.

14. The display device according to claim 13, wherein each of plurality of the source amplifiers comprises a current source configured to generate a bias current used for generating the first drive voltage, and
 wherein, in response to stopping the amplifying operation thereof, each of the plurality of source amplifiers is further configured to:
 stop generating the bias current with the current source; and
 output a second drive voltage corresponding to black portions of the display panel.

15. The display device according to claim 13, wherein each of the amplifier control circuitries is further configured to:
 stop the amplifying operation of the paired source amplifier in response to the image data associated with the paired source amplifier specifying a grayscale value corresponding to a black portion of the display panel.

16. The display device according to claim 13, wherein each of the amplifier control circuitries is further configured to:
 stop the amplifying operation of the paired source amplifier in response to the image data associated with the paired source amplifier specifying a grayscale value corresponding to a black portion of the display panel, execute the amplifying operation of the paired source amplifier in response to the image data associated with the paired source amplifier not specifying the grayscale value corresponding to the black portion of the display panel.

42

17. The display device according to claim 13, wherein the display panel includes a liquid crystal display panel configured to operate in a normally black mode, and
 wherein a voltage level of a second drive voltage corresponding to black portions of the display panel is a circuit ground level of the display driver.

18. The display device according to claim 13, wherein the display panel includes a liquid crystal display panel configured to operate in a normally white mode,
 wherein the plurality of source amplifiers comprises:

a positive side source amplifier configured to output a positive drive voltage with respect to a circuit ground of the display driver; and
 a negative side source amplifier configured to output a negative drive voltage with respect to the circuit ground of the display driver,

wherein a drive voltage corresponding to black portions of the display panel with respect to the positive side source amplifier is a first power supply voltage supplied to the positive side source amplifier, the first power supply voltage being positive with respect to the circuit ground of the display driver, and

wherein the drive voltage corresponding to black portions of the display panel with respect to the positive side source amplifier is a second power supply voltage supplied to the negative side source amplifier, the second power supply voltage being negative with respect to the circuit ground of the display driver.

19. A method comprising:
 driving, based on image data, a plurality of source lines of a display panel, wherein each of the plurality of source lines is paired with a respective one of a plurality of source amplifiers;

processing, via data identification circuitries, the image data associated with each of the source amplifiers, wherein each of the source amplifiers is paired with a respective one of the data identification circuitries; and controlling, via amplifier control circuitries, execution and stopping of an amplifying operation of each of the source amplifiers independently based on the processed image data associated with each of the source amplifiers, wherein each of the data identification circuitries is paired with a respective one of the amplifier control circuitries.

20. The method according to claim 19, wherein each of the source amplifiers comprises a current source configured to generate a bias current used for generating a drive voltage, wherein stopping the amplifying operation is achieved by stopping the generation of the bias current with the current source.
